**5,10-EPOXY-5H-DIBENZO[a,d]CYCLOHEPTENES
AND RELATED COMPOUNDS**

Marcia E. Christy, Box 315H, R.R. 2,
Perkasie, Pa. 18944

No Drawing. Continuation-in-part of application Ser. No. 286,962, June 11, 1963. This application Aug. 23, 1965, Ser. No. 481,908

Int. Cl. C07d 7/10, 5/10; C07c 13/54

U.S. CL. 260—327

88 Claims

This application is a continuation-in-part of copending application Ser. No. 306,639, filed Sept. 4, 1963, now abandoned, which is, in turn, a continuation-in-part of application Ser. No. 286,962, filed June 11, 1963, now abandoned.

This invention relates to derivatives of dibenzocycloheptenes. In particular, the invention relates to 10,11-dihydro-5-(3-substituted-aminopropyl)-5,10-epoxy-5H-dibenzo[a,d]cycloheptenes, 10,11-dihydro-5-(3-substituted-aminopropyl)-5,10-epoxy-11-substituted-5H-dibenzo[a,d]cycloheptenes, and methods of preparing the same. The invention also relates to intermediates useful in the preparation of the above compounds as well as processes for the preparation of said intermediates.

The end compounds embraced within the scope of the present invention may be represented by the following structural formulae

wherein Z is a radical selected from the group consisting of H, OH, OY, =NOR°, =NOY, NH₂, NH₂SO₂R,

=NNH₂; when Z is OH or OY, there can be an alkyl group as defined by R''' replacing the hydrogen at the 11 position; R is lower alkyl, straight or branched chain, preferably having up to 6 carbon atoms,

wherein B is hydrogen, halogen, trifluoromethyl, lower alkyl, straight or branched chain, preferably having up to 4 carbon atoms, lower alkoxy, straight or branched chain, preferably having up to 4 carbon atoms, and n represents a whole number of from 0 to 3; R° is hydrogen or lower alkyl, straight or branched chain, preferably having up to 6 carbon atoms; R' is lower alkyl, straight or branched chain, preferably having up to 6 carbon atoms; R''' is lower alkyl, straight or branched chain, preferably having up to 6 carbon atoms; Y is alkanoyl, straight or branched chain, preferably having up to 18 carbon atoms and may contain unsaturation,

wherein B and n are as defined above; and X and X', which may be similar or dissimilar, are hydrogen, an alkyl group having up to 6 carbon atoms, and alkenyl

2

group having up to 6 carbon atoms, halogen, trifluoromethyl, hydroxyl, an alkoxy group having up to 4 carbon atoms, mercapto, an alkylmercapto group having up to 4 carbon atoms, an alkylsulfonyl group having up to 4 carbon atoms, sulfamoyl, an alkylsulfamoyl group having up to 4 carbon atoms, or a dialkylsulfamoyl group having up to 8 carbon atoms. More than one of these substituents may be on each of the benzenoid rings.

The radicals R' and R'' may be similar or dissimilar and they may be linked together through an atom of carbon, nitrogen or oxygen to form a heterocyclic ring having from 5 to 6 atoms therein such as 1-piperidyl, 1-pyrrolidyl, 4-morpholinyl and 1-loweralkyl-4-piperazinyl, the lower alkyl substituent of the latter preferably having up to 4 carbon atoms.

The compounds represented by the above structural formulae may also have substituents on the propyl side chain such as lower alkyl radicals, preferably having from 1 to 4 carbon atoms.

Representative end compounds encompassed within the scope of the present invention include:

- 10,11-dihydro-5,10-epoxy-11-hydroxy-5-[3-(1-piperidyl)-propyl]-5H-dibenzo[a,d]cycloheptene
- 10,11-dihydro-5,10-epoxy-11-hydroxy-5-[3-(1-methyl-4-piperazinyl)-propyl]-5H-dibenzo[a,d]cycloheptene
- 10,11-dihydro-5,10-epoxy-11-hydroxy-5-(3-dimethylaminopropyl)-5H-dibenzo[a,d]cycloheptene
- 10,11-dihydro-5,10-epoxy-11-hydroxy-5-(3-methylaminopropyl)-5H-dibenzo[a,d]cycloheptene
- 30 7-chloro-10,11-dihydro-5,10-epoxy-11-hydroxy-5-(3-dimethylaminopropyl)-5H-dibenzo[a,d]cycloheptene
- 10,11-dihydro-5-(3-dimethylaminopropyl)-5,10-epoxy-11-hydroxyimino-3-methylsulfonyl-5H-dibenzo[a,d]cycloheptene
- 11-methylamino-10,11-dihydro-5-(3-dimethylamino-propyl)-5,10-epoxy-5H-dibenzo[a,d]cycloheptene
- 11-diethylamino-10,11-dihydro-5-(3-dimethylamino-propyl)-5,10-epoxy-5H-dibenzo[a,d]cycloheptene
- 40 10,11-dihydro-5-(3-dimethylaminopropyl)-5,10-epoxy-11-ethyl-11-hydroxy-5H-dibenzo[a,d]cycloheptene
- 10,11-dihydro-5,10-epoxy-11-hydroxy-5-(3-methylamino-propyl)-3-methylsulfonyl-5H-dibenzo[a,d]cycloheptene
- 45 10,11-dihydro-5,10-epoxy-11-hydroxy-5-(3-dimethyl-aminopropyl)-3-trifluoromethyl-5H-dibenzo[a,d]cycloheptene
- 10,11-dihydro-5,10-epoxy-11-hydroxy-5-(3-diethylamino-propyl)-3-dimethylsulfamoyl-5H-dibenzo[a,d]cycloheptene
- 50 10,11-dihydro-5,10-epoxy-5-(3-dimethylaminopropyl)-5H-dibenzo[a,d]cycloheptene
- 10,11-dihydro-5,10-epoxy-5-(3-dimethylaminopropyl)-5H-dibenzo[a,d]cycloheptene
- 55 10,11-dihydro-5,10-epoxy-5-(3-methylaminopropyl)-3-methylsulfonyl-5H-dibenzo[a,d]cycloheptene
- 10,11-dihydro-5,10-epoxy-5-(3-dimethylaminopropyl)-3-trifluoromethyl-5H-dibenzo[a,d]cycloheptene
- 60 10,11-dihydro-5,10-epoxy-5-(3-diethylaminopropyl)-3-dimethylsulfamoyl-5H-dibenzo[a,d]cycloheptene
- 11-acetoxy-10,11-dihydro-5,10-epoxy-5-(3-methylamino-propyl)-3-trifluoromethyl-5H-dibenzo[a,d]cycloheptene
- 65 11-benzoyloxy-10,11-dihydro-5,10-epoxy-5-(3-methyl-aminopropyl)-5H-dibenzo[a,d]cycloheptene
- 11-p-chlorobenzoyloxy-10,11-dihydro-5-(3-dimethyl-aminopropyl)-5,10-epoxy-5H-dibenzo[a,d]cycloheptene

- 10,11-dihydro-5-(3-dimethylaminopropyl)-5,10-epoxy-11-p-tolyloxy-5H-dibenzo[a,d]cycloheptene
 10,11-dihydro-5-(3-dimethylaminopropyl)-5,10-epoxy-11-p-methoxybenzoyloxy-5H-dibenzo[a,d]cycloheptene
 10,11-dihydro-5-(3-dimethylaminopropyl)-5,10-epoxy-11-m-trifluoromethylbenzoyloxy-5H-dibenzo[a,d]cycloheptene
 10,11-dihydro-5,10-epoxy-5-(3-methylaminopropyl)-11-phenylacetoxo-5H-dibenzo[a,d]cycloheptene
 10,11-dihydro-5-(3-dimethylaminopropyl)-5,10-epoxy-11-hydrocinnamoyloxy-5H-dibenzo[a,d]cycloheptene
 10,11-dihydro-5,10-epoxy-5-(3-methylaminopropyl)-11-propionyloxy-5H-dibenzo[a,d]cycloheptene
 11-acetoxyimino-10,11-dihydro-5-(3-dimethylamino-
 propyl)-3-dimethylsulfamoyl-5,10-epoxy-5H-dibenzo[a,d]cycloheptene
 11-benzoyloxyimino-10,11-dihydro-5,10-epoxy-5-(3-methylaminopropyl)-5H-dibenzo[a,d]cycloheptene
 10,11-dihydro-5-(3-dimethylaminopropyl)-5,10-epoxy-11-phenylacetoxoimino-5H-dibenzo[a,d]cycloheptene
 11-p-chlorobenzoyloxyimino-10,11-dihydro-5-(3-dimethylaminopropyl)-5,10-epoxy-5H-dibenzo[a,d]cycloheptene
 10,11-dihydro-5-(3-dimethylaminopropyl)-5,10-epoxy-11-p-tolyloxyimino-5H-dibenzo[a,d]cycloheptene
 10,11-dihydro-5-(3-dimethylaminopropyl)-5,10-epoxy-11-phenylacetoxoimino-5H-dibenzo[a,d]cycloheptene
 10,11-dihydro-5-(3-dimethylaminopropyl)-5,10-epoxy-11-hydrocinnamoyloxyimino-5H-dibenzo[a,d]cycloheptene
 10,11-dihydro-5-(3-dimethylaminopropyl)-5,10-epoxy-11-propoxyimino-5H-dibenzo[a,d]cycloheptene
 11-benzenesulfonamido-10,11-dihydro-5-(3-dimethylamino-
 propyl)-5,10-epoxy-5H-dibenzo[a,d]cycloheptene
 10,11-dihydro-5-(3-dimethylaminopropyl)-5,10-epoxy-11-p-toluenesulfonamido-5H-dibenzo[a,d]cycloheptene
 10,11-dihydro-5-(3-dimethylaminopropyl)-5,10-epoxy-11-phenylmethanesulfonamido-5H-dibenzo[a,d]cycloheptene
 10,11-dihydro-5-(3-dimethylaminopropyl)-5,10-epoxy-5H-dibenzo[a,d]cycloheptene-N-oxide
 10,11-dihydro-11-dimethylamino-5,10-epoxy-5-(3-dimethylaminopropyl)-5H-dibenzo[a,d]cycloheptene-N,N'-dioxide

The compounds represented by the above structural formulae can advantageously be employed in pharmaceutical applications because they have been found to possess anti-depressant activity. As anti-depressants, they may be administered orally in the form of tablets, powders, sustained release pellets and the like or they may be administered orally or parenterally in the form of aqueous solutions or suspensions. When administered orally or parenterally, satisfactory results are obtained at a daily dosage level of from about one mg. to about 300 mgs., preferably given in divided doses over the day or in sustained release form. The compounds are preferably administered in the form of their non-toxic acid addition salts and these salts are included within the scope of this invention. In addition, the compounds represented by structural Formula I may be converted to the N-oxides. These compounds, as well as their acid addition salts, possess anti-depressant activity and are also included within the scope of this invention.

The compounds of structural Formula I, wherein Z is hydroxyl and X, X', R' and R'' are as defined, may be prepared by treating a 3a,12 β -dihydro-8H-dibenzo[3,4:6,7]-cyclohepta[1,2-d]-1,3-dioxol-8-one with a Grignard reagent, namely, a tertiaryaminopropylmagnesium halide, and the Grignard adduct obtained hydrolyzed to form the corresponding 3a,12 β -dihydro-8-hydroxy-8-(3-tertiaryaminopropyl)-8H-dibenzo[3,4:6,7]-cyclohepta

[1,2-d]-1,3-dioxole. The latter compound then is hydrolyzed under suitable conditions to effect ring closure and form the corresponding 10,11-dihydro-5,10-epoxy-11-hydroxy-5-(3-tertiaryaminopropyl)-5H-dibenzo[a,d]cycloheptene. This process may be illustrated as follows:

In the above process, Hal represents halogen, preferably chlorine or bromine, R' and R'' are as previously defined and R^{IV} and R^V are hydrogen, alkyl, aryl or aralkyl or may be linked together to form a ring having 5 to 8 carbon atoms.

The starting compound, wherein X and X' are both hydrogen and R^{IV} and R^V are both methyl, namely, the 3a,12 β -dihydro-2,2-dimethyl-8H-dibenzo[3,4:6,7]-cyclohepta[1,2-d]-1,3-dioxol-8-one, may be prepared in the manner described by G. L. Buchanan and D. B. Jhaveri in the J. Org. Chem., 26, 4295-4299 (1961). Those starting compounds, wherein at least one of X and X' is other than hydrogen, may be prepared from the corresponding nucleophilic substituted 5H-dibenzo[a,d]cyclohepten-5-one utilizing the procedure of G. L. Buchanan and D. B. Jhaveri referred to above. The latter compounds may be prepared following the teachings of T. W. Campbell et al. in an article appearing in Helv. Chem. Acta, vol. 36, pp. 1489-1499 (1953), or as described in the examples.

Those starting compounds, wherein R^{IV} and R^V are other than methyl, may be prepared from the corresponding diol by treatment with an appropriate aldehyde or ketone utilizing the procedure described by G. L. Buchanan and D. B. Jhaveri for the preparation of the acetonide of the trans diol appearing in the article referred to above.

It should be noted that inasmuch as the R^{IV} and R^V substituents are removed during the preparation of the end compounds of the invention, the selection of the particular starting compound with respect to these substituents will be dependent only upon their ease of preparation and the removal of the R^{IV} and R^V substituents during subsequent hydrolysis.

The Grignard reagent employed in Step A of the above process may be prepared by known procedures, but it has been found that it may be prepared in high yields as follows:

It has been found that the use of tetrahydrofuran as the solvent for the reaction results in a rapid production of the Grignard reagent in high yield.

5

The reaction with the Grignard reagent (Step A) is preferably initially carried out at low temperature such as is obtained by the use of an ice-bath and finally may continue at room temperature. It has been found that tetrahydrofuran is a suitable solvent for carrying out the reaction and, accordingly, the ketone may be added directly to the reaction mixture in which the Grignard reagent was prepared. However, any inert solvent for the reactants may be employed.

After the addition reaction is completed, the bulk of the solvent is removed by vacuum distillation, the Grignard adduct dissolved in a suitable solvent such as benzene, and hydrolyzed by the addition of water or ammonium chloride solution with cooling. The product is recovered by evaporation of the solvent after the removal of any residual inorganic material by decantation or filtration.

Conversion of the carbinol to the corresponding 5,10-epoxy-11-hydroxy derivative (Step B) is effected by hydrolyzing the former in a suitable solvent, preferably at elevated temperatures, and in the presence of an acidic catalyst such as, for example, p-toluenesulfonic acid, sulfuric acid, trifluoroacetic acid, hydrochloric acid and the like. A variety of solvents may be utilized, but it is preferred to employ a lower alkanol such as methanol, ethanol, propanol-2 and the like. Where the product is insoluble in the solvent employed, it may be recovered (as the salt) by filtration, and further purified by conventional methods. Where the product is soluble in the solvent employed, it may be recovered (as the base) by evaporation of the solvent, diluting with water, neutralizing any residual acid with sufficient alkali to render the medium basic and collecting the precipitate which forms by filtration.

The preparation of those compounds represented by structural Formula I, wherein Z is hydrogen and X, X', R' and R'' are as defined, may be accomplished from the corresponding 11-hydroxy compound obtained in Step B. This process may be illustrated as follows:

6

The conversion of the 11-hydroxy compound to the corresponding 11-keto compound can be effected employing the standard Oppenauer oxidation reaction. If desired, the product may be isolated in conventional manner. Conversion of the ketone to the corresponding thioketal (Step D) is accomplished by contacting the former with a dithiol such as ethylene dithiol or trimethylene dithiol in the presence of boron trifluoride etherate or zinc chloride-hydrochloric acid and the like. The resulting product which, if desired, can be isolated by conventional methods, is then desulfurized employing Raney nickel in a suitable solvent such as a lower alkanol, preferably ethanol. The product may be recovered by evaporation of the solvent.

The preparation of those compounds represented by structural Formula II, wherein Z is limited to hydrogen, can be readily effected by dealkylation of the corresponding compound of structural Formula I, wherein R' and R'' are both lower alkyl, and preferably are the same. This process may be illustrated as follows:

wherein X, X' and R' are as previously defined and R^{VI} is alkyl, aralkyl or aryl. It will be readily appreciated by those skilled in the art that inasmuch as the R^{VI} substituent is removed during the dealkylation, the selection of the particular haloformate will be limited only by its availability and subsequent ease of hydrolysis of the intermediate urethane produced.

The preparation of those compounds of structural Formula II, wherein Z is hydroxy, can be readily accomplished by dealkylating the corresponding 11-hydroxy compound of structural Formula I employing a haloformate as illustrated above. However, if it is desired the hydroxy group may be protected during the reaction with the haloformate. This is readily accomplished by acylating the starting 5-(3-dialkylaminopropyl)-10,11-dihydro-5,10-epoxy-11-hydroxy - 5H - dibenz[a,d]cycloheptene (Step F) employing any of the common acylating agents. The preferred acylating agents are the acid anhydrides, such as acetic anhydride, since they can serve as both solvent and reagent. Once having obtained the acylated

derivative, the dealkylation may proceed as indicated by Steps G and H. This process may be illustrated as follows:

wherein X, X', R', and Y are as previously defined. Insofar as the substituent Y is concerned, the selection thereof is not critical and is dependent only on the stability of the acylating agent and the ease of hydrolysis of the acyl moiety.

Step G of the above-illustrated processes involves the condensation of the tertiary amino compound with a haloformate to form the corresponding urethane. While the reaction with the haloformate can be carried out in the absence of a solvent, it is preferable to employ an excess of the haloformate. Other suitable solvents include the aromatic hydrocarbons such as benzene and toluene, aliphatic hydrocarbons such as heptane and hexane, and the halogenated hydrocarbons such as chloroform and carbon tetrachloride. The reaction may be carried out at room temperature, although an elevated temperature is preferred. At the conclusion of the reaction, the urethane intermediate is recovered in conventional manner.

The urethane intermediate thus produced then is subjected to hydrolysis (Step H). The hydrolysis of the urethane is preferably carried out under basic conditions. After completion of the hydrolysis, the desired product is recovered in conventional manner, such as by extraction into a suitable solvent and evaporation of the solvent.

If it is desired, the compounds represented by structural Formula II, wherein Z is hydrogen, also may be prepared by first dealkylating the 5-(3-dialkylaminopropyl)-10,11-dihydro-5,11-epoxy-11-hydroxy- 5H - dibenzo [a,d]cycloheptene or 11-acyloxy derivative thereof, in the manner described in Steps F, G and H above, to form the corresponding 5-(3-alkylaminopropyl)-10,11-dihydro-5,10-epoxy-11-hydroxy-5H-dibenzo[a,d]cycloheptene and then converting the latter to the corresponding 5-(3-alkylaminopropyl) - 10,11 - dihydro - 5,10 - epoxy-5H-dibenzo[a,d]cycloheptene, following the procedure described in Steps C, D and E above.

As noted hereinabove, the acylated compounds that are obtained in Step F as intermediates also possess significant anti-depressant activity. The same is true with respect to the acylated compounds included in structural Formulae I and II hereinabove where R' and R'' are as defined. The 11-acyloxy compounds included in structural Formula I are readily prepared by acylating the corresponding 11-hydroxy compound obtained in Step B in the manner described in Step F hereinabove. The 11-acyloxy compounds included in structural Formula II may also be prepared following the general procedure

of Step F, except that it is necessary to carry out the acylation employing an acid addition salt of the 5,10-

epoxy-11-hydroxy - 5 - (3-alkylaminopropyl)-derivative, preferably a salt derived from a strong acid such as, for example, the hydrochloride.

The preparation of those compounds represented by structural Formula I, wherein Z is a substituted imino radical ($=NOR^{\circ}$) and R°, R', R'', X, and X' are as defined, may be accomplished by treating the 11-keto compound obtained in Step C with hydroxylamine or an appropriately substituted hydroxylamine. This process may be illustrated as follows:

The conversion of the 11-keto compound to the corresponding 11-hydroxyimino compound is preferably carried out in the presence of a suitable solvent and at elevated temperatures, preferably the reflux temperature of the mixture. Suitable solvents which may be employed are the lower alkanols and, of these, methanol is preferred. However, other inert organic solvents that are capable of solubilizing the hydroxylamine reagent also may be used. After completion of the reaction, the solvent is removed as by distillation, the residue dissolved in water and the solution rendered alkaline. The precipitated product that separates is readily recovered by filtration.

The preparation of those compounds represented by structural Formula II, wherein Z is a substituted imino radical ($=NOR^{\circ}$) and R°, R', X and X' are as defined, is readily effected by first oxidizing the above 11-hydroxy compound of Step H, wherein R' is as defined, following the procedure of Step C hereinabove and then treating the corresponding 11-keto derivative with hydroxylamine re-

agent as described in Step I. This process may be illustrated as follows:

wherein R° , R' , X and X' are as previously defined.

The preparation of those compounds of structural Formulae I and II, wherein Z is amino and R' , R'' , X and X' are as defined, is accomplished by reducing the corresponding oxime obtained in Step I. The reduction is preferably accomplished using metallic sodium in ethanol, although other conventional reducing agents such as the metal hydrides as well as catalytic hydrogenation may be employed. The desired product may be readily recovered by conventional methods.

The compounds of structural Formula I wherein Z is alkylamino or dialkylamino are readily prepared by alkylating the corresponding amino compound. The alkylation is accomplished in known manner by reductive alkylation employing an appropriate aldehyde or ketone to give the corresponding monoalkylamino derivative. The corresponding dimethylamino derivative can be prepared employing formaldehyde and formic acid by conventional procedures.

Alternatively, the mono and dialkylamines can be prepared in conventional manner by acylating the primary amine with, for example, acetic anhydride, propionic anhydride or butyric anhydride to form the corresponding

amide, and then reducing the latter to the secondary amine using a suitable reducing agent such as lithium

aluminum hydride. The dialkylamines can be obtained from monoalkylamines by again acylating and then reducing the secondary amide. The preparation of those compounds of structural Formula I, wherein R° and R''' are different, can be readily achieved by appropriate selection of the acylating agent, or in the case of the dialkylamines, wherein one of the alkyl radicals is methyl, by subjecting the secondary amine prepared via the acylation and reduction route to reductive alkylation using formaldehyde. The compounds of structural Formula II, wherein Z is alkylamino or dialkylamino, are prepared by treating the 11-keto compound obtained from Step C (wherein R' and R'' are the same) with a haloformate as described in Step G to form the corresponding 11-keto urethane. The 11-keto urethane is then treated with hydroxylamine or a derivative thereof, as described in Step I, to form the corresponding oxime and the oxime reduced to the corresponding primary amine employing sodium and alcohol or catalytic hydrogenation. The primary amine can then be alkylated using the processes described above and the resulting 11-alkyl or dialkylamino urethane hydrolyzed as described in Step H. This overall process may be represented as follows:

The preparation of those compounds of structural Formula I wherein Z is a substituted sulfonamido radical (NHSO_2R) and R, R', R'', X and X' are as defined, is accomplished by treating the corresponding 11-amino derivative with an appropriate sulfonyl halide or sulfonic anhydride. This process may be illustrated as follows:

wherein R, R', R'', X and X' are as previously defined and Hal represents halogen, preferably chlorine or bromine. The introduction of the sulfonyl moiety is accomplished in conventional manner employing such solvents and conditions as are well known in the art. The corresponding sulfonylamino derivatives of compounds of structural Formula II are readily prepared by dealkylating the compound obtained from Step I wherein R' and R'' are both lower alkyl and preferably are the same. This process may be illustrated as follows:

wherein R, R', R^{VI}, X and X' are as previously defined.

The preparation of those compounds of structural Formulae I and II, wherein the 11-position contains both a hydroxyl and lower alkyl substituent, wherein R', R'', R^{VI}, X and X' are as defined, may be accomplished by treating the corresponding 5-(3-tertiaryaminopropyl)-11-keto compound obtained in Step C with an appropriate Grignard reagent, namely, an alkylmagnesium halide and then hydrolyzing the resulting Grignard adduct following the procedure of Step A. The corresponding secondary aminopropyl derivative of structural Formula II can be prepared by dealkylating the 11-alkyl-11-hydroxy-5-(3-tertiaryaminopropyl) derivative obtained above following the procedures of Steps G and H or, if desired, the 11-keto-5-(3-alkylaminopropyl) derivative obtained in Step C can be condensed directly with the Grignard reagent and the Grignard adduct hydrolyzed as described above.

The compounds of structural Formula I wherein Z is the radical $=\text{NOY}$ and R', R'', X, X' and Y are as defined are readily prepared by acylating the corresponding 11-hydroxyimino obtained in Step I in the manner described in Step F. The 11-acyloxyimino compounds of structural Formula II are prepared in similar manner from the corresponding 11-hydroxyimino-5-(3-alkylaminopropyl) derivative obtained in Step I except as noted hereinabove

with respect to the acylation of the 11-hydroxy compounds of structural Formula II, the acylation is carried out employing a salt of the 5,10-epoxy-11-hydroxyimino-5-(3-alkylaminopropyl) derivative.

The compounds of structural Formulas I and II wherein Z is the hydrazone radical ($=\text{NNH}_2$) and R', R'', X

and X' are as defined are prepared by reacting the corresponding 11-keto compound obtained in Step C with hydrazine following the procedure described by D. H. R. Barton, R. G. O'Brien, and S. Sternhell in J. Chem. Soc., p. 470 (1962).

The preparation of those compounds of structural Formulae I and II wherein Z is OY and an alkyl group replaces hydrogen at the 11 position and R', R'', R^{VI}, X, X' and Y are as defined, is accomplished by acylating the

corresponding 11-alkyl-11-hydroxy derivative in the manner described in Step F. However, with respect to the preparation of the 11-alkyl-11-acyloxy compounds of structural Formula II, the acylation is carried out in the same manner as previously mentioned for the preparation of the 11-hydroxy and 11-acyloxyimino compounds of structural Formula II, i.e. employing a salt of the 11-alkyl-5,10-epoxy-11-hydroxy-5-(3-alkylaminopropyl) derivative.

As previously indicated hereinabove, the instant invention includes within its scope the acid addition salts of the compounds represented by structural Formulae I and II, the N-oxides of the compounds represented by structural Formula I, and the acid addition salts of the latter. The acid addition salts are readily prepared by reaction of the free base or N-oxide as the case may be with a suitable acid in known manner. The N-oxides of the compounds represented by structural Formula I are conveniently prepared in conventional manner by treating a compound of structural Formula I, in free base form, with hydrogen peroxide in an inert, organic solvent such as a lower alkanol, preferably methanol.

It will be appreciated by those skilled in the art that the compounds represented by structural Formulae I and II hereinabove, wherein the 11-carbon atom carries two dis-

13

similar substituents, exist as geometric isomers. The geometric isomers exist as racemates and resolution into enantiomorphs is possible by conventional techniques, such as fractional crystallization of the salts with optically active acids. Where Z is hydroxy, the separate geometric isomers can be obtained by starting with the desired isomer of the ketone employed in Step A. Such isomers can be obtained utilizing the procedure described in an article by G. L. Buchanan et al., referred to hereinabove. While both isomers possess pharmacological activity, the activity of one isomer may be substantially greater than the other.

When the 11-position is substituted by an oximino or hydrazone radical, another type of geometric isomerism is possible depending on whether the substituent is syn or anti to the oxygen bridge.

It is to be noted that when the carbinols obtained in Step A above contain a nuclear substituent, conversion to the 5,10-epoxy-11-hydroxy derivative (Step B) may give either or both of two compounds depending upon the direction of the ring closure. Thus, when a 6-substituted carbinol is used, the product may be the 3- and/or 7-substituted-5,10-epoxy-11-hydroxy derivative, and the designation 3(7) is employed, when applicable, in the following examples which describe the preparation of representative compounds encompassed within the scope of the present invention.

EXAMPLE 1

Cis $3\alpha,12\beta$ -dihydro-2-phenyl-8H-dibenzo[3,4:6,7]-cyclohepta[1,2-d]-1,3-dioxol-8-one

A solution of cis 10,11-dihydro-10,11-dihydroxy-5H-dibenzo[a,d]cyclohepten-5-one (2.4 g., 0.01 mole) and p-toluenesulfonic acid monohydrate (25 mg., 0.00013 mole) in 100 ml. of dry benzene is stirred and heated to refluxing. The solvent is distilled slowly and after approximately 5 ml. of distillate is collected, 5 ml. of freshly distilled benzaldehyde is added to the mixture. Stirring and slow distillation are continued for 1 hour. After the addition of 1 ml. of pyridine, the mixture is evaporated to dryness under reduced pressure. Crystallization of the solid residue from absolute ethanol gives the product, M.P. 167-175° C., in a yield of 1.3 g. (40%). An analytical sample melts at 175-176.5° C. after repeated recrystallizations from absolute ethanol.

Analysis.—Calc'd for $C_{22}H_{16}O_3$: C, 80.47; H, 4.91. Found: C, 80.38; H, 5.04.

EXAMPLE 2

Cis $3\alpha,12\beta$ -dihydro-2,2-dimethyl-8-(3-dimethylaminopropyl)-8-hydroxy-8H-dibenzo[3,4:6,7]cyclohepta[1,2-d]-1,3-dioxole

3-dimethylaminopropylmagnesium chloride is prepared

50

55

14

from magnesium turnings (290 mg., 0.012 g. atom) and 3-dimethylaminopropyl chloride (1.47 g., 0.012 mole) in 12 ml. of dry tetrahydrofuran following the method of U.S. Patent No. 3,046,283. In a nitrogen atmosphere, a solution of cis $3\alpha,12\beta$ -dihydro-2,2-dimethyl-8H-dibenzo[3,4:6,7]cyclohepta[1,2-d]-1,3-dioxol-8-one (1.7 g., 0.0061 mole) in 13 ml. of dry tetrahydrofuran is added dropwise to the stirred solution of the Grignard reagent while cooling in an ice-bath. The dark yellow solution is allowed to come to room temperature and stirred for 2 hours. The bulk of the solvent then is distilled at room temperature under reduced pressure. The residue is dissolved in 25 ml. of benzene, and water, 6 ml., is added dropwise with stirring and cooling. The benzene layer is decanted from the gelatinous precipitate which then is extracted with three 30 ml. portions of boiling benzene. The combined benzene extracts are washed with water repeatedly. The benzene is evaporated and the residual solid crystallized from 95% ethanol. Cis $3\alpha,12\beta$ -dihydro-2,2-dimethyl-8-(3-dimethylaminopropyl)-8-hydroxy-8H-dibenzo[3,4:6,7]cyclohepta[1,2-d]-1,3-dioxole is obtained as white needles, M.P. 181-188° C., in a yield of 1.56 g. (70%). The pure product from another experiment melts at 189-190° C. after recrystallization from 95% ethanol and from isopropyl alcohol.

Analysis.—Calc'd for $C_{23}H_{29}O_3N$: C, 75.17; H, 7.95; N, 3.81. Found: C, 75.12; H, 7.82; N, 4.01.

EXAMPLE 3

Cis $3\alpha,12\beta$ -dihydro-8-(3-dimethylaminopropyl)-8-hydroxy-2-phenyl-8H-dibenzo[3,4:6,7]cyclohepta[1,2-d]-1,3-dioxole

35

By following the procedure of Example 2, but using an equimolecular quantity of cis $3\alpha,12\beta$ -dihydro-2-phenyl-8H-dibenzo[a,d]cyclohepta[1,2-d]-1,3-dioxol-8-one instead of the cis $3\alpha,12\beta$ -dihydro-2,2-dimethyl-8H-dibenzo[3,4:6,7]cyclohepta[1,2-d]-1,3-dioxol-8-one, there is obtained cis $3\alpha,12\beta$ -dihydro-8-(3-dimethylaminopropyl)-8-hydroxy-2-phenyl-8H-dibenzo[3,4:6,7]cyclohepta[1,2-d]-1,3-dioxole as a white crystalline solid, M.P. 155-161° C., in a yield of 71%. Repeated recrystallizations from 95% ethanol give an analytical sample, M.P. 166-167° C.

Analysis.—Calc'd for $C_{27}H_{29}NO_3$: C, 78.04; H, 7.04; N, 3.37. Found: C, 78.09; H, 7.21; N, 3.42.

EXAMPLE 4

Following the procedure of Example 2, the products enumerated below are obtained using the ketone of Example 2 and the Grignard reagent designated below.

Grignard reagent	Product
3-diethylaminopropylmagnesium chloride	cis 8-(3-diethylaminopropyl)- $3\alpha,12\beta$ -dihydro-2,2-dimethyl-8-hydroxy-8H-dibenzo[3,4:6,7]cyclohepta[1,2-d]-1,3-dioxole.
3-(1-pyrrolidyl)-propylmagnesium chloride	Cis $3\alpha,12\beta$ -dihydro-2,2-dimethyl-8-hydroxy-8-[3-(1-pyrrolidyl)-propyl]-8H-dibenzo[3,4:6,7]cyclohepta[1,2-d]-1,3-dioxole.
3-(1-piperidyl)-propylmagnesium chloride	Cis $3\alpha,12\beta$ -dihydro-2,2-cimethyl-8-hydroxy-8-[3-(1-piperidyl)-propyl]-8H-dibenzo[3,4:6,7]cyclohepta[1,2-d]-1,3-dioxole.
3-(1-ethyl-4-piperazinyl)-propylmagnesium chloride	Cis $3\alpha,12\beta$ -dihydro-2,2-dimethyl-8-[3-(1-ethyl-4-piperazinyl)-propyl]-8-hydroxy-8H-dibenzo[3,4:6,7]cyclohepta[1,2-d]-1,3-dioxole.
3-(4-morpholinyl)-propylmagnesium chloride	Cis $3\alpha,12\beta$ -dihydro-2,2-dimethyl-8-hydroxy-8-[3-(4-morpholinyl)-propyl]-8H-dibenzo[3,4:6,7]cyclohepta[1,2-d]-1,3-dioxole.
3-(N-ethyl-N-methylamino)propylmagnesium chloride	Cis $3\alpha,12\beta$ -dihydro-2,2-dimethyl-8-[3-(N-ethyl-N-methylamino)-propyl]-8-hydroxy-8H-dibenzo[3,4:6,7]cyclohepta[1,2-d]-1,3-dioxole.

EXAMPLE 5

Following the procedure of Example 2, the products enumerated below are obtained using the Grignard reagent of Example 2 and the ketone designated below

Ketone	Product
Cis 3 α ,12 β -dihydro-8H-dibenzo[3,4:6,7]cyclohepta[1,2-d]-1,3-dioxol-8-one	Cis 3 α ,12 β -dihydro-8-(3-dimethylaminopropyl)-8-hydroxy-8H-dibenzo[3,4:6,7]cyclohepta[1,2-d]-1,3-dioxole.
Cis 3 α ,12 β -dihydro-2-methyl-8H-dibenzo[3,4:6,7]cyclohepta[1,2-d]-1,3-dioxol-8-one.	Cis 3 α ,12 β -dihydro-8-(3-dimethylaminopropyl)-8-hydroxy-2-methyl-8H-dibenzo[3,4:6,7]cyclohepta[1,2-d]-1,3-dioxole.
Cis 2-benzyl-3 α ,12 β -dihydro-8H-dibenzo[3,4:6,7]cyclohepta[1,2-d]-1,3-dioxol-8-one.	Cis 2-benzyl-3 α ,12 β -dihydro-8-(3-dimethylaminopropyl)-8-hydroxy-8H-dibenzo[3,4:6,7]cyclohepta[1,2-d]-1,3-dioxole.
Cis 3 α ,12 β -dihydro-2-ethyl-2-methyl-8H-dibenzo[3,4:6,7]cyclohepta[1,2-d]-1,3-dioxol-8-one.	Cis 3 α ,12 β -dihydro-8-(3-dimethylaminopropyl)-2-ethyl-8-hydroxy-2-methyl-8H-dibenzo[3,4:6,7]cyclohepta[1,2-d]-1,3-dioxole.
Cis 3 α ,12 β -dihydro-2,2-dimethyl-6-methylsulfonyl-8H-dibenzo[3,4:6,7]cyclohepta[1,2-d]-1,3-dioxol-8-one.	Cis 3 α ,12 β -dihydro-2,2-dimethyl-8-(3-dimethylaminopropyl)-8-hydroxy-6-methylsulfonyl-8H-dibenzo[3,4:6,7]cyclohepta[1,2-d]-1,3-dioxole.
Cis 6-chloro-3 α ,12 β -dihydro-2,2-dimethyl-8H-dibenzo[3,4:6,7]cyclohepta[1,2-d]-1,3-dioxol-8-one.	Cis 6-chloro-3 α ,12 β -dihydro-2,2-dimethyl-8-(3-dimethylaminopropyl)-8-hydroxy-8H-dibenzo[3,4:6,7]cyclohepta[1,2-d]-1,3-dioxole.
Cis 3 α ,12 β -dihydro-2,2-dimethyl-6-dimethylsulfamoyl-8H-dibenzo[3,4:6,7]cyclohepta[1,2-d]-1,3-dioxol-8-one.	Cis 3 α ,12 β -dihydro-2,2-dimethyl-8-(3-dimethylaminopropyl)-6-dimethylsulfamoyl-8-hydroxy-8H-dibenzo[3,4:6,7]cyclohepta[1,2-d]-1,3-dioxole.

EXAMPLE 6

Cis 10,11-dihydro-5-(3-dimethylaminopropyl)-5,10-epoxy-11-hydroxy-5H-dibenzo[a,d]cycloheptene

A solution of cis 3 α ,12 β -dihydro-2,2-dimethyl-8-(3-dimethylaminopropyl)-8-hydroxy-8H-dibenzo[3,4:6,7]cyclohepta[1,2-d]-1,3-dioxole (2.95 g., 0.008 mole) and p-toluenesulfonic acid monohydrate (3.0 g., 0.0158 mole) in 300 ml. of absolute methanol is heated to refluxing for 4 hours. The solution is neutralized with 16 ml. of 1 M potassium hydroxide in methanol and then the solvent is distilled under reduced pressure. The residue is partitioned between benzene and water and the aqueous layer re-extracted twice with benzene. The combined benzene extracts are washed with water, dried by filtration through paper, and then evaporated to dryness under reduced pressure. Crystallization of the residual solid from 50% ethanol gives the product, M.P. 145-152° C., in a yield of 1.9 g. (81%). An analytical sample melts at 151-153° C. after repeated crystallizations from cyclohexane.

Analysis.—Calc'd for C₂₀H₂₃NO₂: C, 77.64; H, 7.49; N, 4.53. Found: C, 77.67; H, 7.70; N, 4.52.

EXAMPLE 7

Cis 10,11-dihydro-5-(3-dimethylaminopropyl)-5,10-epoxy-11-hydroxy-5H-dibenzo[a,d]cycloheptene

A solution of cis 3 α ,12 β -dihydro-8-(3-dimethylaminopropyl)-8-hydroxy-2-phenyl-8H-dibenzo[3,4:6,7]cyclohepta[1,2-d]-1,3-dioxole (415 mg., 0.001 mole) and p-toluenesulfonic acid monohydrate (380 mg., 0.002 mole) in 40 ml. of absolute methanol is heated to refluxing for 8 hours. The cooled solution is made basic with 5 ml. of 1 M potassium hydroxide in methanol and the solvent is distilled under reduced pressure. The residue is partitioned between benzene and water and after re-extraction of the aqueous phase with benzene, the combined benzene extracts are washed with water and dried by filtration through anhydrous sodium sulfate. Evaporation of the benzene under reduced pressure leaves an oily residue which solidifies upon trituration with ether, yielding 200 mg. (65%), M.P. 137-144° C. A purified sample is identical in melting point (149-152° C.), mixture melting point and infrared spectrum to cis 10,11-dihydro-5-(3-dimethylaminopropyl)-5,10-epoxy-11-hydroxy-5H-dibenzo[a,d]cycloheptene, prepared as in Example 6.

EXAMPLE 8

Employing the procedure of Example 6, the products enumerated below are obtained using the products enu-

merated in Examples 4 and 5 in place of the dioxole used in Example 6.

cis 5-(3-diethylaminopropyl)-10,11-dihydro-5,10-epoxy-11-hydroxy-5H-dibenzo[a,d]cycloheptene

cis 10,11-dihydro-5,10-epoxy-11-hydroxy-5-[3-(1-pyrrolidyl)-propyl]-5H-dibenzo[a,d]cycloheptene
 cis 10,11-dihydro-5,10-epoxy-11-hydroxy-5-[3-(1-piperidyl)-propyl]-5H-dibenzo[a,d]cycloheptene
 cis 10,11-dihydro-5,10-epoxy-5-[3-(1-ethyl-4-piperazinyl)-propyl]-11-hydroxy-5H-dibenzo[a,d]cycloheptene
 cis 10,11-dihydro-5,10-epoxy-11-hydroxy-5-[3-(4-morpholinyl)-propyl]-5H-dibenzo[a,d]cycloheptene
 cis 10,11-dihydro-5,10-epoxy-5-[3-(N-ethyl-N-methylamino)-propyl]-11-hydroxy-5H-dibenzo[a,d]cycloheptene
 cis 10,11-dihydro-5-(3-dimethylaminopropyl)-5,10-epoxy-11-hydroxy-3(7)-methylsulfonyl-5H-dibenzo[a,d]cycloheptene
 cis 3(7)-chloro-10,11-dihydro-5-(3-dimethylaminopropyl)-5,10-epoxy-11-hydroxy-5H-dibenzo[a,d]cycloheptene
 cis 10,11-dihydro-5-(3-dimethylaminopropyl)-3(7)-dimethylsulfamoyl-5,10-epoxy-11-hydroxy-5H-dibenzo[a,d]cycloheptene

EXAMPLE 9

Trans 3 α ,12 β -dihydro-2,2-dimethyl-8-(3-dimethylaminopropyl)-8-hydroxy-8H-dibenzo[3,4:6,7]cyclohepta[1,2-d]-1,3-dioxole

3-dimethylaminopropylmagnesium chloride is prepared from magnesium turnings (4.05 g., 0.166 g. atom) and 3-dimethylaminopropyl chloride (20.2 g., 0.166 mole) in 150 ml. of dry tetrahydrofuran, following the method of U.S. Patent No. 3,046,283. In a nitrogen atmosphere, a solution of trans 3 α ,12 β -dihydro-2,2-dimethyl-8H-dibenzo[3,4:6,7]cyclohepta[1,2-d]-1,3-dioxol-8-one (23.2 g., 0.083 mole) in 100 ml. of dry tetrahydrofuran is added dropwise to the stirred solution of the Grignard reagent while cooling in an ice-bath. The mixture is allowed to come to room temperature and stirred for 2 hours. The bulk of the solvent then is distilled below 50° C., under reduced pressure. The residue is dissolved in 150 ml. of benzene, and water, 20 ml., is added dropwise with stirring and cooling. The benzene layer is decanted from the gelatinous precipitate which then is extracted with four 100 ml. portions of boiling benzene. The combined benzene extracts are washed with water and extracted with three 100 ml. portions of 0.5 M citric acid. The acid extract is made basic with sodium hydroxide and the oily base that separates is extracted into benzene. After washing the combined extracts with water and drying over anhydrous sodium sulfate, the benzene is evaporated and the product obtained as a viscous yellow oil in a yield of 29.5 g. (96%).

The base may be converted to the hydrogen oxalate salt by treating an ethereal solution with a solution of oxalic acid (10% excess) in isopropyl alcohol. The trans $3\alpha,12\beta$ -dihydro - 2,2 - dimethyl - 8 - (3-dimethylaminopropyl) - 8 - hydroxy - 8H - dibenzo - [3,4:6,7]cyclohepta[1,2-d]-1,3-dioxole hydrogen oxalate is obtained as a white crystalline solid, M.P. 169-172° C., dec. Repeated recrystallizations from mixtures of isopropyl alcohol and absolute ether give the product, M.P. 171-173° C., dec.

Analysis.—Calc'd for $C_{23}H_{29}NO_3 \cdot C_2H_2O_4$: C, 65.62; H, 6.83. Found: C, 65.08; H, 6.72.

EXAMPLE 10

Following the procedure of Example 9, the products enumerated below are obtained using the ketone of Example 9 and the Grignard reagent designated below.

Grignard reagent	Product
3-diethylaminopropylmagnesium chloride	Trans 8-(3-diethylamino-propyl)- $3\alpha,12\beta$ -dihydro-2,2-dimethyl-8-hydroxy-8H-dibenzo-[3,4:6,7]cyclohepta[1,2-d]-1,3-dioxole.
3-(1-pyrrolidyl)-propylmagnesium chloride	Trans 3 $\alpha,12\beta$ -dihydro-2,2-dimethyl-8-hydroxy-8-[3-(1-pyrrolidyl)-propyl]-8H-dibenzo-[3,4:6,7]cyclohepta[1,2-d]-1,3-dioxole.
3-(1-piperidyl)-propylmagnesium chloride	Trans 3 $\alpha,12\beta$ -dihydro-2,2-dimethyl-8-hydroxy-8-[3-(1-piperidyl)-propyl]-8H-dibenzo-[3,4:6,7]cyclohepta[1,2-d]-1,3-dioxole.
3-(1-ethyl-4-piperazinyl)-propylmagnesium chloride	Trans 3 $\alpha,12\beta$ -dihydro-2,2-dimethyl-8-[3-(1-ethyl-4-piperazinyl)-propyl]-8-hydroxy-8H-dibenzo-[3,4:6,7]cyclohepta[1,2-d]-1,3-dioxole.
3-(4-morpholinyl)-propyl magnesium chloride	Trans 3 $\alpha,12\beta$ -dihydro-2,2-dimethyl-8-hydroxy-8-[3-(4-morpholinyl)-propyl]-8H-dibenzo-[3,4:6,7]cyclohepta[1,2-d]-1,3-dioxole.
3-(N-ethyl-N-methylamino)-propylmagnesium chloride	Trans 3 $\alpha,12\beta$ -dihydro-2,2-dimethyl-8-[3-(N-ethyl-N-methylamino)-propyl]-8-hydroxy-8H-dibenzo[3,4:6,7]cyclohepta[1,2-d]-1,3-dioxole.

EXAMPLE 11

Following the procedure of Example 9, the products enumerated below are obtained using the Grignard reagent of Example 9 and the ketone designated below.

18

from a mixture of benzene and cyclohexane affords the white crystalline product, M.P. 156-160° C., in a yield of 18 g. (73%). The pure product melts at 157-158° C. after recrystallization from benzene and sublimation at 140° C. and 0.01 mm.

Analysis.—Calc'd for $C_{20}H_{23}NO_2$: C, 77.64; H, 7.49; N, 4.53. Found: C, 77.73; H, 7.71; N, 4.73.

EXAMPLE 13

Employing the procedure of Example 12, the products enumerated below are obtained using the products enumerated in Examples 10 and 11 in place of the dioxole used in Example 12.

trans 5-(3-diethylaminopropyl)-10,11-dihydro-5,10-epoxy-11-hydroxy-5H-dibenzo[a,d]cycloheptene cycloheptene

trans 10,11-dihydro-5,10-epoxy-11-hydroxy-5-[3-(1-pyrrolidyl)-propyl]-5H-dibenzo[a,d]cycloheptene
trans 10,11-dihydro-5,10-epoxy-11-hydroxy-5-[3-(1-piperidyl)-propyl]-5H-dibenzo[a,d]cycloheptene

Ketone	Product
Trans 3 $\alpha,12\beta$ -dihydro-8H-dibenzo[3,4:6,7]cyclohepta[1,2-d]-1,3-dioxol-8-one	Trans 3 $\alpha,12\beta$ -dihydro-8-(3-dimethylaminopropyl)-8-hydroxy-8H-dibenzo[3,4:6,7]cyclohepta[1,2-d]-1,3-dioxole.
Trans 3 $\alpha,12\beta$ -dihydro-2-phenyl-8H-dibenzo[3,4:6,7]cyclohepta[1,2-d]-1,3-dioxol-8-one.	Trans 3 $\alpha,12\beta$ -dihydro-8-(3-dimethylaminopropyl)-8-hydroxy-2-phenyl-8H-dibenzo[3,4:6,7]cyclohepta[1,2-d]-1,3-dioxole.

Trans 3 $\alpha,12\beta$ -dihydro-2,2-dimethyl-6-methylsulfonyl-8H-dibenzo[3,4:6,7]cyclohepta[1,2-d]-1,3-dioxol-8-one.	Trans 3 $\alpha,12\beta$ -dihydro-2,2-dimethyl-8-(3-dimethylaminopropyl)-8-hydroxy-6-methylsulfonyl-8H-dibenzo[3,4:6,7]cyclohepta[1,2-d]-1,3-dioxole.
Trans 6-chloro-3 $\alpha,12\beta$ -dihydro-2,2-dimethyl-8H-dibenzo[3,4:6,7]cyclohepta[1,2-d]-1,3-dioxol-8-one.	Trans 6-chloro-3 $\alpha,12\beta$ -dihydro-2,2-dimethyl-8-(3-dimethylaminopropyl)-8-hydroxy-8H-dibenzo[3,4:6,7]cyclohepta[1,2-d]-1,3-dioxole.
Trans 3 $\alpha,12\beta$ -dihydro-2,2-dimethyl-6-dimethyl-sulfamoyl-8H-dibenzo[3,4:6,7]cyclohepta[1,2-d]-1,3-dioxol-8-one.	Trans 3 $\alpha,12\beta$ -dihydro-2,2-dimethyl-8-(3-dimethylaminopropyl)-6-dimethyl-sulfamoyl-8-hydroxy-8H-dibenzo[3,4:6,7]cyclohepta[1,2-d]-1,3-dioxole.

EXAMPLE 12

Trans 10,11-dihydro-5-(3-dimethylaminopropyl)-5,10-epoxy-11-hydroxy-5H-dibenzo[a,d]cycloheptene

A solution of trans $3\alpha,12\beta$ -dihydro-2,2-dimethyl-8-(3-dimethylaminopropyl)-8-hydroxy-8H-dibenzo[3,4:6,7]cyclohepta[1,2-d]-1,3-dioxole (29.4 g., 0.08 mole) and p-toluenesulfonic acid monohydrate (30.5 g., 0.16 mole) in 2.3 l. of absolute methanol is heated to refluxing for 4 hours. The cooled solution is neutralized with 150 ml. of 1 M potassium hydroxide in methanol and the solvent then is distilled under reduced pressure. The residue is partitioned between benzene and 5% aqueous sodium hydroxide and water and the aqueous layer is re-extracted with three portions of benzene. The combined benzene extracts are washed with water, dried by filtration through anhydrous sodium sulfate, and evaporated to dryness under reduced pressure. Crystallization of the residual solid

trans 10,11-dihydro-5,10-epoxy-5-[3-(1-ethyl-4-piperazinyl)-propyl]-11-hydroxy-5H-dibenzo[a,d]cycloheptene
trans 10,11-dihydro-5,10-epoxy-11-hydroxy-5-[3-(4-morpholinyl)-propyl]-5H-dibenzo[a,d]cycloheptene
trans 10,11-dihydro-5,10-epoxy-5-[3-(N-ethyl-N-methylamino)-propyl]-11-hydroxy-5H-dibenzo[a,d]cycloheptene
trans 10,11-dihydro-5-(3-dimethylaminopropyl)-5,10-epoxy-11-hydroxy-3(7)-methylsulfonyl-5H-dibenzo[a,d]cycloheptene
trans 3(7)-chloro-10,11-dihydro-5-(3-dimethylaminopropyl)-5,10-epoxy-11-hydroxy-5H-dibenzo[a,d]cycloheptene
trans 10,11-dihydro-5-(3-dimethylaminopropyl)-3(7)-dimethylsulfamoyl-5,10-epoxy-11-hydroxy-5H-dibenzo[a,d]cycloheptene

EXAMPLE 14

Cis 11-acetoxy-10,11-dihydro-5-(3-dimethylamino-propyl)-5,10-epoxy-5H-dibenzo[a,d]cycloheptene

A solution of cis 10,11-dihydro-5-(3-dimethylamino-propyl)-5,10-epoxy-11-hydroxy-5H-dibenzo[a,d]cycloheptene (630 mg., 0.00204 mole) in 12 ml. of acetic anhydride is heated to refluxing for 4½ hours. The dark yellow solution is evaporated to dryness under reduced pressure and the oily residue dissolved in 20 ml. of water containing 1 ml. of 6 N hydrochloric acid. After one extraction with benzene, the aqueous solution is rendered alkaline with sodium hydroxide and the oily base extracted into benzene. The washed benzene extract is evaporated under reduced pressure, leaving the product as an oily residue weighing, typically, 600 mg. (84%).

The base may be converted to the hydrogen oxalate salt by treating a solution in isopropyl alcohol with a solution of oxalic acid (10% excess) in isopropyl alcohol. Cis 11-acetoxy-10,11-dihydro-5-(3-dimethylamino-propyl)-5,10-epoxy-5H-dibenzo[a,d]cycloheptene hydrogen oxalate is obtained as a white crystalline solid, M.P. 171-173° C., dec. Repeated recrystallizations from isopropyl alcohol and from mixtures of absolute ethanol and absolute ether give the product, M.P. 173-175° C., dec.

Analysis.—Calc'd for $C_{22}H_{25}NO_3 \cdot C_2H_2O_4$: C, 65.29; H, 6.16; N, 3.17. Found: C, 65.27; H, 6.40; N, 3.06.

EXAMPLE 15

Following the procedure of Example 14, the products enumerated below are obtained employing the acylating agents designated below in place of acetic anhydride used in Example 14.

Acyllating agent	Product
Propionic anhydride.....	cis 10,11-dihydro-5-(3-dimethylaminopropyl)-5,10-epoxy-11-propionyloxy-5H-dibenzo[a,d]cycloheptene.
Butyryl chloride/pyridine....	Cis 11-butyryloxy-10,11-dihydro-5-(3-dimethylaminopropyl)-5,10-epoxy-5H-dibenzo[a,d]cycloheptene.
Benzoyl chloride/pyridine....	Cis 11-benzoyloxy-10,11-dihydro-5-(3-dimethylaminopropyl)-5,10-epoxy-5H-dibenzo[a,d]cycloheptene.
Caproyl chloride/pyridine....	Cis 11-caproyloxy-10,11-dihydro-5-(3-dimethylaminopropyl)-5,10-epoxy-5H-dibenzo[a,d]cycloheptene.

EXAMPLE 16

Following the procedure of Example 14, the products enumerated below are obtained employing, in place of cis 10,11-dihydro-5-(3-dimethylaminopropyl)-5,10-epoxy-11-hydroxy-5H-dibenzo[a,d]cycloheptene, the reactants designated below.

Reactant	Product
Cis 5-(3-diethylaminopropyl)-10,11-dihydro-5,10-epoxy-11-hydroxy-5H-dibenzo[a,d]cycloheptene.	Cis 11-acetoxy-5-(3-diethylaminopropyl)-10,11-dihydro-5,10-epoxy-5H-dibenzo[a,d]cycloheptene.
Cis 10,11-dihydro-5-(3-dimethylaminopropyl)-5,10-epoxy-11-hydroxy-3(7)-methylsulfonyl-5H-dibenzo[a,d]cycloheptene.	Cis 11-acetoxy-10,11-dihydro-5-(dimethylaminopropyl)-5,10-epoxy-3(7)-methylsulfonyl-5H-dibenzo[a,d]cycloheptene.
Cis 3(7)-chloro-10,11-dihydro-5-(3-dimethylaminopropyl)-5,10-epoxy-11-hydroxy-5H-dibenzo[a,d]cycloheptene.	Cis 11-acetoxy-3(7)-chloro-10,11-dihydro-5-(dimethylaminopropyl)-5,10-epoxy-5H-dibenzo[a,d]cycloheptene.
Cis 10,11-dihydro-5-(3-dimethylaminopropyl)-3(7)-dimethylsulfamoyl-5,10-epoxy-11-hydroxy-5H-dibenzo[a,d]cycloheptene.	Cis 11-acetoxy-10,11-dihydro-5-(3-dimethylaminopropyl)-3(7)-dimethylsulfamoyl-5,10-epoxy-5H-dibenzo[a,d]cycloheptene.

EXAMPLE 17

Cis 11-acetoxy-5-[3-(N-carbethoxy-N-methylamino)-propyl]-10,11-dihydro-5,10-epoxy-5H-dibenzo[a,d]cycloheptene

A solution of cis 11-acetoxy-10,11-dihydro-5-(3-dimethylaminopropyl)-5,10-epoxy-5H-dibenzo[a,d]

70

20

cycloheptene (600 mg., 0.00172 mole) in 3 ml. of dry benzene is added dropwise to a stirred solution of 0.7 ml. of ethyl chloroformate in 2 ml. of dry benzene. A yellow gum separates, but dissolves upon warming the mixture. After stirring for 1 hour at reflux, the mixture is cooled, diluted with benzene, and washed with 2 N hydrochloric acid, then with water. Evaporation of the benzene under reduced pressure leaves the product as an oily residue weighing, typically, 650 mg. (92.5%).

EXAMPLE 18

Following the procedure of Example 17, the products enumerated below are obtained using the products enumerated in Examples 15 and 16 in place of the dibenzo-cycloheptene compound used in Example 17.

- 10 cis 5-[3-(N-carbethoxy-N-methylamino)-propyl]-10,11-dihydro-5,10-epoxy-11-propionyloxy-5H-dibenzo[a,d]cycloheptene
 15 cis 11-butyryloxy-5-[3-(N-carbethoxy-N-methylamino)-propyl]-10,11-dihydro-5,10-epoxy-5H-dibenzo[a,d]cycloheptene
 20 cis 11-benzoyloxy-5-[3-(N-carbethoxy-N-methylamino)-propyl]-10,11-dihydro-5,10-epoxy-5H-dibenzo[a,d]cycloheptene
 25 cis 11-acetoxy-5-[3-(N-carbethoxy-N-methylamino)-propyl]-10,11-dihydro-5,10-epoxy-5H-dibenzo[a,d]cycloheptene
 30 cis 11-acetoxy-5-[3-(N-carbethoxy-N-ethylamino)-propyl]-10,11-dihydro-5,10-epoxy-5H-dibenzo[a,d]cycloheptene
 cis 11-acetoxy-5-[3-(N-carbethoxy-N-methylamino)-propyl]-10,11-dihydro-5,10-epoxy-3(7)-methylsulfonyl-5H-dibenzo[a,d]cycloheptene
 cis 11-acetoxy-3(7)-chloro-5-[3-(N-carbethoxy-N-methylamino)-propyl]-10,11-dihydro-5,10-epoxy-5H-dibenzo[a,d]cycloheptene

50 cis 11-acetoxy-5-[3-(N-carbethoxy-N-methylamino)-propyl]-10,11-dihydro-3(7)-dimethylsulfamoyl-5,10-epoxy-5H-dibenzo[a,d]cycloheptene
 cis 11-caproyloxy-5-[3-(N-carbethoxy-N-methylamino)-propyl]-10,11-dihydro-5,10-epoxy-5H-dibenzo[a,d]cycloheptene

EXAMPLE 19

Following the procedure of Example 17, the products enumerated below are obtained employing the haloformate designated below.

75

Halogenate	Product
Benzyl chloroformate	Cis 11-acetoxy-5-[3-(N-carbobenzoxy-N-methylamino)-propyl]-10,11-dihydro-5,10-epoxy-5H-dibenzo[a,d]cycloheptene.
Phenyl chloroformate	Cis 11-acetoxy-5-[3-(N-carboxyphenoxy-N-methylamino)-propyl]-10,11-dihydro-5,10-epoxy-5H-dibenzo[a,d]cycloheptene.
Propyl chloroformate	Cis 11-acetoxy-5-[3-(N-carboxypropoxy-N-methylamino)-propyl]-10,11-dihydro-5,10-epoxy-5H-dibenzo[a,d]cycloheptene.

EXAMPLE 20

10

Cis 10,11 - dihydro - 5,10-epoxy-11-hydroxy-5-(3-methyl-aminopropyl)-5H-dibenzo[a,d]cycloheptene

A solution of the crude urethane obtained in Example 17 (650 mg., 0.00159 mole) and potassium hydroxide (500 mg., 0.0089 mole) in 10 ml. of n-butyl alcohol is stirred and heated to refluxing in a nitrogen atmosphere for 7 hours. The solvent is evaporated under reduced pressure and the residue partitioned between benzene and water. After two re-extractions of the aqueous phase, the combined benzene extracts are washed with water and then extracted with 15 ml. and 10 ml. portions of 0.5 M citric acid. The benzene layer then is washed with water. Evaporation of the solvent under reduced pressure leaves the neutral materials, *cis* 5-[3-(N - carbethoxy-N-methylamino)-propyl]-10,11 - dihydro - 5,10 - epoxy - 11-hydroxy - 5H - dibenzo-[a,d]cycloheptene, as an oily residue weighing, typically 300 mg. The citric acid extract is rendered alkaline with sodium hydroxide and the oily base extracted into benzene. The washed benzene extract is evaporated to dryness under reduced pressure. Crystallization of the residue from absolute ether gives the product as a white crystalline solid, M.P. 128-130° C., in a yield of 110 mg.

A solution of the neutral material and potassium hydroxide (250 mg., 0.0045 mole) in 4 ml. of *n*-butyl alcohol is stirred and heated to refluxing in a nitrogen atmosphere for 10 hours. The reaction mixture is worked up as described above and the basic material crystallized from absolute ether to obtain additional product, M.P. 126-128° C., in a yield of 70 mg. The combined products (180 mg., 35%) are purified by recrystallization from absolute ether and sublimation at reduced pressure gives an analytical sample which melts at 138-139° C.

Analysis.—Calc'd for $C_{19}H_{21}NO_2$: C, 77.25; H, 7.17; N, 4.74. Found: C, 77.07; H, 6.95; N, 4.91.

EXAMPLE 22

Trans 11-acetoxy-10,11-dihydro-5-(3-dimethylaminopropyl)-5-10-exopy-5H-dibenzo[a,d]cycloheptene

By replacing the cis 10,11-dihydro-5-(3-dimethylamino-propyl)-5,10- epoxy - 11 - hydroxy-5H-dibenzo[a,d]cycloheptene used in Example 14 with an equimolecular amount of the trans isomer and following substantially the same procedure described in Example 14, there is obtained trans 11-acetoxy-10,11-dihydro-5-(3-dimethylamino-propyl)-5,10- epoxy - 5H - dibenzo[a,d]cycloheptene. The yield of white crystalline base, M.P. 116.5-120° C., is 79%. An analytical sample melts at 125-126° C. after recrystallization from petroleum ether.

Analysis.—Calc'd for $C_{22}H_{25}NO_3$: C, 75.18; H, 7.17; N, 3.99. Found: C, 74.93; H, 7.04; N, 3.94.

EXAMPLE 23

Following the procedure of Example 22, the products enumerated below are obtained employing the acylating agents enumerated in Example 15.

trans 10,11-dihydro-5-(3-dimethylaminopropyl)-5,10-
    epoxy-11-propionyloxy-5-H-dibenzo[a,d]cycloheptene
trans 11-butyryloxy-10,11-dihydro-5-(3-dimethylamino-
    propyl)-5,10-epoxy-5H-dibenzo[a,d]cycloheptene
trans 11-benzyloxy-10,11-dihydro-5-(3-dimethylamino-
    propyl)-5,10-epoxy-5H-dibenzo[a,d]cycloheptene
trans 11-caproyloxy-10,11-dihydro-5-(3-dimethylamino-
    propyl)-5,10-epoxy-5H-dibenzo[a,d]cycloheptene

EXAMPLE 24

Following the procedure of Example 22, the products enumerated below are obtained employing in place of trans 10,11 - dihydro - 5 - (3 - dimethylaminopropyl)-5,10-epoxy-11-hydroxy-5H-dibenzo[a,d]cycloheptene, the reactants designated below.

Reactant	Product
Trans 5-(3-diethylaminopropyl)-10,11-dihydro-5,10-epoxy-11-hydroxy-5H-dibenzo[a,d]cycloheptene.	Trans 11-acetoxy-5-(3-diethylaminopropyl)-10,11-dihydro-5,10-epoxy-5H-dibenzo[a,d]cycloheptene.
Trans 10,11-dihydro-5-(3-dimethylaminopropyl)-5,10-epoxy-11-hydroxy-3(7)-methylsulfonyl-5H-dibenzo[a,d]cycloheptene.	Trans 11-acetoxy-10,11-dihydro-5-(3-dimethylaminopropyl)-5,10-epoxy-3(7)-methylsulfonyl-5H-dibenzo[a,d]cycloheptene.
Trans 3(7)-chloro-10,11-dihydro-5-(3-dimethylaminopropyl)-5,10-epoxy-11-hydroxy-5H-dibenzo[a,d]cycloheptene.	Trans 11-acetoxy-3(7)-chloro-10,11-dihydro-5-(3-dimethylaminopropyl)-5,10-epoxy-5H-dibenzo[a,d]cycloheptene.
Trans 10,11-dihydro-5-(3-dimethylaminopropyl)-3(7)-dimethylsulfamoyl-5,10-epoxy-11-hydroxy-5H-dibenzo[a,d]cycloheptene.	Trans 11-acetoxy-10,11-dihydro-5-(3-dimethylaminopropyl)-3(7)-dimethylsulfamoyl-5,10-epoxy-5H-dibenzo[a,d]cycloheptene.

EXAMPLE 21

Following the procedure of Example 20, the products enumerated below are obtained employing the products enumerated in Examples 18 and 19 in place of the urethane used in Example 20. 60

cis 10,11 - dihydro - 5,10 - epoxy - 11 - hydroxy-5-(3-methylamino-propyl)-5H-dibenzo[a,d]cycloheptene
 cis 10,11 - dihydro - 5,10-epoxy-5-(3-ethylaminopropyl)-11-hydroxy-5H-dibenzo[a,d]cycloheptene
 cis 10,11 - dihydro - 5,10-epoxy-11-hydroxy-5-(3-methylamino-propyl)-3(7) - methylsulfonyl - 5H - dibenzo[a,d]cycloheptene
 cis 3(7) - chloro - 10,11 - dihydro-5,10-epoxy-11-hydroxy-5-(3-methylaminopropyl) - 5H - dibenzo[a,d]cycloheptene
 cis 10,11 - dihydro - 3(7) - dimethylsulfamoyl - 5,10-epoxy - 11 - hydroxy - 5 - (3 - methylaminopropyl)-5H-dibenzo[a,d]cycloheptene

EXAMPLE 25

Trans 11-acetoxy-5-[3-(N - carbethoxy-N - methylamino)-propyl]-10,11 - dihydro-5,10-epoxy - 5H-dibenzo[a,d]-cycloheptene

Trans 11 - acetoxy - 10,11-dihydro-5-(3-dimethylamino-propyl)-5,10-epoxy-5H-dibenzo[a,d]cycloheptene, 5.5 g. (0.0157 mole), is added in small portions with stirring to 150 ml. of ethyl chloroformate cooled in an ice-bath. The mixture is stirred in the cold for 1½ hours, then heated to refluxing for 16 hours. Excess ethyl chloroformate is distilled under reduced pressure and the oily residue treated with benzene and the mixture evaporated to dryness under reduced pressure. This treatment is repeated and the residue finally is partitioned between benzene and water. The benzene layer is washed with water, 0.5 M citric acid, and water, dried by filtration through anhydrous sodium sulfate, and evaporated to dryness under reduced pressure. Crystallization of the oily residue

from ether-petroleum ether gives the product, M.P. 75-76° C., a yield of 2.4 g. A second crop of 2.0 g., M.P. 72-73° C., is obtained from the mother liquor. A purified sample melts at 77-78° C. after recrystallization from a mixture of absolute ether and petroleum ether.

Analysis.—Calc'd for $C_{24}H_{27}NO_5$: C, 70.40; H, 6.65. Found: C, 69.78; H, 6.80.

EXAMPLE 26

Following the procedure of Example 25, the products enumerated below are obtained employing the products enumerated in Examples 23 and 24 in place of the dibenzocycloheptane compound used in Example 25.

trans 5-[3-(N-carbethoxy-N-methylamino)-propyl]-10,11-dihydro-5,10-epoxy-11-propionyloxy-5H-dibenzo[a,d]-cycloheptene
 trans 11-butyryloxy-5-[3-(N-carbethoxy-N-methylamino)-propyl]-10,11-dihydro-5,10-epoxy-5H-dibenzo[a,d]-cycloheptene
 trans 11-benzoyloxy-5-[3-(N-carbethoxy-N-methylamino)-propyl]-10,11-dihydro-5,10-epoxy-5H-dibenzo[a,d]-cycloheptene
 trans 11-acetoxy-5-[3-(N-carbethoxy-N-ethylamino)-propyl]-10,11-dihydro-5,10-epoxy-5H-dibenzo[a,d]-cycloheptene
 trans 11-acetoxy-5-[3-(N-carbethoxy-N-methylamino)-propyl]-10,11-dihydro-5,10-epoxy-3(7)-methylsulfonyl-5H-dibenzo[a,d]-cycloheptene
 trans 11-acetoxy-3(7)-chloro-5-[3-(N-carbethoxy-N-methylamino)-propyl]-10,11-dihydro-5,10-epoxy-5H-dibenzo[a,d]-cycloheptene
 trans 11-acetoxy-5-[3-(N-carbethoxy-N-methylamino)-propyl]-10,11-dihydro-3(7)-dimethylsulfamoyl-5,10-epoxy-5H-dibenzo[a,d]-cycloheptene
 trans 11-caproyloxy-5-[3-(N-carbethoxy-N-methylamino)-propyl]-10,11-dihydro-5,10-epoxy-5H-dibenzo[a,d]-cycloheptene

EXAMPLE 27

Following the procedure of Example 25, the products enumerated below are obtained employing the haloformate enumerated in Example 19.

Haloformate	Product
Benzyl chloroformate.....	Trans 11-acetoxy-5-[3-(N-carbobenzoxy-N-methylamino)-propyl]-10,11-dihydro-5,10-epoxy-5H-dibenzo[a,d]-cycloheptene
Phenyl chloroformate.....	Trans 11-acetoxy-5-[3-(N-carbophenoxy-N-methylamino)-propyl]-10,11-dihydro-5,10-epoxy-5H-dibenzo[a,d]-cycloheptene
Propyl chloroformate.....	Trans 11-acetoxy-5-[3-(N-carbopropoxy-N-methylamino)-propyl]-10,11-dihydro-5,10-epoxy-5H-dibenzo[a,d]-cycloheptene

EXAMPLE 28

Trans 10,11-dihydro-5,10-epoxy-11-hydroxy-5-(3-methylaminopropyl)-5H-dibenzo[a,d]-cycloheptene

A solution of trans 11-acetoxy-5-[3-(N-carbethoxy-N-methylamino)-propyl]-10,11-dihydro-5,10-epoxy-5H-dibenzo[a,d]-cycloheptene (4.1 g., 0.01 mole) and potassium hydroxide (20 g., 0.0358 mole) in 100 ml. of n-butyl alcohol is stirred and heated to refluxing in a nitrogen atmosphere for 11 hours. The solvent is evaporated under reduced pressure and the residue partitioned between benzene and water. After two re-extractions of the aqueous phase, the combined benzene extracts are washed with water and then extracted with three 100 ml. portions of 0.5 M citric acid. The citric acid extract is rendered alkaline with sodium hydroxide and the oily base extracted into benzene. The washed benzene extract is dried by filtration through anhydrous sodium sulfate and evaporated to dryness under reduced pressure. Crystallization of the oily residue from a mixture of absolute ether and petroleum ether gives the product as a white

crystalline solid, M.P. 128-129° C., in a yield of 1.5 g. (51%). An analytical sample melts at 129-130° C. after sublimation at 115° C. and 0.1 mm.

Analysis.—Calc'd for $C_{19}H_{21}NO_2$: C, 77.25; H, 7.17; N, 4.74. Found: C, 77.33; H, 7.20; N, 4.94.

EXAMPLE 29

Following the procedure of Example 28, the products enumerated below are obtained employing the products enumerated in Examples 26 and 27 in place of the urethane used in Example 28.

trans 10,11-dihydro-5,10-epoxy-11-hydroxy-5-(3-methylaminopropyl)-5H-dibenzo[a,d]-cycloheptene
 trans 10,11-dihydro-5,10-epoxy-5-(3-ethylaminopropyl)-11-hydroxy-5H-dibenzo[a,d]-cycloheptene
 trans 10,11-dihydro-5,10-epoxy-11-hydroxy-5-(3-methylaminopropyl)-3(7)-methylsulfonyl-5H-dibenzo[a,d]-cycloheptene
 trans 3(7)-chloro-10,11-dihydro-5,10-epoxy-11-hydroxy-5-(3-methylaminopropyl)-5H-dibenzo[a,d]-cycloheptene
 trans 10,11-dihydro-3(7)-dimethylsulfamoyl-5,10-epoxy-11-hydroxy-5-(3-methylaminopropyl)-5H-dibenzo[a,d]-cycloheptene

EXAMPLE 30

10,11-dihydro-5-(3-dimethylaminopropyl)-5,10-epoxy-11-keto-5H-dibenzo[a,d]-cycloheptene

A solution of trans 10,11-dihydro-5-(3-dimethylaminopropyl)-5,10-epoxy-11-hydroxy-5H-dibenzo[a,d]-cycloheptene (6.18 g., 0.02 mole) and 60 ml. of freshly distilled cyclohexanone in 600 ml. of dry toluene is heated to boiling and 250 ml. of toluene is distilled. Slow distillation is continued while a solution of aluminum isopropoxide (8.0 g., 0.039 mole) in 400 ml. of dry toluene is added dropwise over a 1 hour period and for an additional 30 minutes. The mixture is cooled in ice and hydrolyzed by the addition of 100 ml. of a saturated aqueous solution of Rochelle salt. The aqueous layer is separated and re-extracted twice with benzene. After washing with water, the combined organic layers are extracted with 200 ml. of 0.5 M citric acid. The citric acid

extract is cooled in an ice-bath, rendered alkaline with sodium hydroxide and the oily base extracted into benzene. The washed and dried benzene extract is evaporated under reduced pressure to give the product as a crystalline residue, M.P. 67-69° C., in a yield of 6.05 g. (98.5%).

An analytical sample melts at 76-78° C. after repeated recrystallizations from hexane.

Analysis.—Calc'd for $C_{20}H_{21}NO_2$: C, 78.14; H, 6.89; N, 4.56. Found: C, 78.22; H, 6.99; N, 4.49.

EXAMPLE 31

Following the procedure of Example 30, the products enumerated below are obtained employing the products enumerated in Example 13 in place of the dibenzocycloheptene used in Example 30.

10,11-dihydro-5-(3-diethylaminopropyl)-5,10-epoxy-11-keto-5H-dibenzo[a,d]-cycloheptene
 10,11-dihydro-5,10-epoxy-11-keto-5-[3-(1-pyrrolidyl)-propyl]-5H-dibenzo[a,d]-cycloheptene
 10,11-dihydro-5,10-epoxy-11-keto-5-[3-(1-piperidyl)-propyl]-5H-dibenzo[a,d]-cycloheptene

25

10,11-dihydro-5,10-epoxy-5-[3-(1-ethyl-4-piperazinyl)-propyl]-11-keto-5H-dibenzo[a,d]cycloheptene-
 10,11-dihydro-5,10-epoxy-11-keto-5-[3-(4-morpholinyl)-propyl]-5H-dibenzo[a,d]cycloheptene
 10,11-dihydro-5,10-epoxy-5-[3-(N-ethyl-N-methylamino)-propyl]-11-keto-5H-dibenzo[a,d]cycloheptene
 10,11-dihydro-5-(3-dimethylaminopropyl)-5,10-epoxy-11-keto-3(7)-methylsulfonyl-5H-dibenzo[a,d]cycloheptene
 3(7)-chloro-10,11-dihydro-5-(3-dimethylaminopropyl)-5,10-epoxy-11-keto-5H-dibenzo[a,d]cycloheptene
 10,11-dihydro-5-(3-dimethylaminopropyl)-3(7)-dimethylsulfamoyl-5,10-epoxy-11-keto-5H-dibenzo[a,d]cycloheptene

EXAMPLE 32

spiro[10,11-dihydro - 5-(3-dimethylaminopropyl) - 5,10-epoxy-5H-dibenzo[a,d]cycloheptene]-11,2'-m-dithiane

A solution of 10,11-dihydro-5-(3-dimethylaminopropyl) - 5,10-epoxy - 11-keto-5H-dibenzo[a,d]cycloheptene (900 mg., 0.003 mole) and 1 ml. of trimethylene dithiol in 20 ml. of glacial acetic acid is stirred and treated with 2 ml. of redistilled boron trifluoride etherate. After stirring 1½ hours at room temperature, the clear yellow solution is allowed to stand overnight. The solution then is poured into 300 ml. of ice-cold 5% aqueous sodium hydroxide. The precipitate is collected, washed with water, air-dried and dissolved in 150 ml. of absolute ether. After removing the insoluble material by filtration, the ether is distilled under reduced pressure. The white crystalline solid residue weighs 1.1 g. (92.5%), M.P. 122-126° C. The pure product melts at 130.5-132° C. after repeated crystallizations from mixtures of ethanol and water and from isopropyl alcohol.

Analysis.—Calc'd for $C_{23}H_{27}NOS_2$: C, 69.47; H, 6.85; N, 3.52. Found: C, 69.19; H, 6.82; N, 3.40.

EXAMPLE 33

Following the procedure of Example 32, the products enumerated below are obtained employing the products enumerated in Example 31 in place of the 11-keto compound used in Example 32.

spiro[10,11-dihydro-5-(3-diethylaminopropyl)-5,10-epoxy-5H-dibenzo[a,d]cycloheptene]-11,2'-m-dithiane
 spiro[10,11-dihydro-5,10-epoxy-5-(3-(1-pyrrolidyl)-propyl)-5H-dibenzo[a,d]cycloheptene]-11,2'-m-dithiane
 spiro[10,11-dihydro-5,10-epoxy-5-(3-(1-piperidyl)-propyl)-5H-dibenzo[a,d]cycloheptene]-11,2'-m-dithiane
 spiro[10,11-dihydro-5,10-epoxy-5-(3-(1-ethyl-4-piperazinyl)-propyl)-5H-dibenzo[a,d]cycloheptene]-11,2'-m-dithiane
 spiro[10,11-dihydro-5,10-epoxy-5-(3-(4-morpholinyl)-propyl)-5H-dibenzo[a,d]cycloheptene]-11,2'-m-dithiane

spiro[10,11-dihydro-5,10-epoxy-5-(3-(N-ethyl-N-methylamino)-propyl)-5H-dibenzo[a,d]cycloheptene]-11,2'-m-dithiane
 spiro[10,11-dihydro-5-(3-dimethylaminopropyl)-5,10-epoxy-3(7)-methylsulfonyl-5H-dibenzo[a,d]cycloheptene]-11,2'-m-dithiane
 spiro[3(7)-chloro-10,11-dihydro-5-(3-dimethylaminopropyl)-5,10-epoxy-5H-dibenzo[a,d]cycloheptene]-11,2'-m-dithiane
 spiro[10,11-dihydro-5-(3-dimethylaminopropyl)-3(7)-dimethylsulfamoyl-5,10-epoxy-5H-dibenzo[a,d]cycloheptene]-11,2'-m-dithiane

EXAMPLE 34

Following the procedure of Example 32, the products enumerated below are obtained employing the compounds enumerated in Example 31 and ethylene dithiol in place

26

of the 11-keto compound and trimethylene dithiol used in Example 32.

spiro[10,11-dihydro-5-(3-diethylaminopropyl)-5,10-epoxy-5H-dibenzo[a,d]cycloheptene]-11,2'-(1',3'-dithiolane)
 spiro[10,11-dihydro-5,10-epoxy-5-(3-(1-pyrrolidyl)-propyl)-5H-dibenzo[a,d]cycloheptene]-11,2'-(1',3'-dithiolane)
 spiro[10,11-dihydro-5,10-epoxy-5-(3-(1-piperidyl)-propyl)-5H-dibenzo[a,d]cycloheptene]-11,2'-(1',3'-dithiolane)
 spiro[10,11-dihydro-5,10-epoxy-5-(3-(1-ethyl-4-piperazinyl)-propyl)-5H-dibenzo[a,d]cycloheptene]-11,2'-(1',3'-dithiolane)
 spiro[10,11-dihydro-5,10-epoxy-5-(3-(4-morpholinyl)-propyl)-5H-dibenzo[a,d]cycloheptene]-11,2'-(1',3'-dithiolane)
 spiro[10,11-dihydro-5,10-epoxy-5-(3-(N-ethyl-N-methylamino)-propyl)-5H-dibenzo[a,d]cycloheptene]-11,2'-(1',3'-dithiolane)
 spiro[10,11-dihydro-5-(3-dimethylaminopropyl)-5,10-epoxy-3(7)-methylsulfonyl-5H-dibenzo[a,d]cycloheptene]-11,2'-(1',3'-dithiolane)
 spiro[3(7)-chloro-10,11-dihydro-5-(3-dimethylaminopropyl)-5,10-epoxy-5H-dibenzo[a,d]cycloheptene]-11,2'-(1',3'-dithiolane)
 spiro[10,11-dihydro-5-(3-dimethylaminopropyl)-3(7)-dimethylsulfamoyl-5,10-epoxy-5H-dibenzo[a,d]cycloheptene]-11,2'-(1',3'-dithiolane)

EXAMPLE 35

10,11-dihydro-5-(3-dimethylaminopropyl)-5,10-epoxy-5H-dibenzo[a,d]cycloheptene

A solution of spiro[10,11-dihydro-5-(3-dimethylaminopropyl)-5,10-epoxy-5H-dibenzo[a,d]-cycloheptene] - 11,2'-m-dithiane (600 mg., 0.0015 mole) in 75 ml. of absolute ethanol is stirred and heated to refluxing with 7 g. of Raney nickel for 24 hours. The nickel is removed by filtration through a mat of diatomaceous earth and washed with absolute ethanol. The alcoholic filtrate is evaporated under reduced pressure, the residual oil dissolved in benzene and the solution again evaporated under reduced pressure, leaving the product as a colorless oily residue weighing 200 mg.

The base may be converted to the hydrogen maleate salt by treating an ethanolic solution with a solution of maleic acid (10% excess) in absolute ether. Further dilution with absolute ether precipitates 10,11-dihydro-5-(3-dimethylaminopropyl) - 5,10 - epoxy-5H-dibenzo-[a,d]cycloheptene hydrogen maleate as a white crystalline solid, M.P. 135-138° C. An analytical sample melts at 141.5-143.5° C. after repeated crystallizations from mixtures of isopropyl alcohol and absolute ether.

Analysis.—Calc'd for $C_{20}H_{23}NO \cdot C_4H_4O_4$: C, 70.41; H, 6.65; N, 3.42. Found: C, 70.61; H, 6.75; N, 3.45.

EXAMPLE 36

Following the procedure of Example 35, the products enumerated below are obtained employing the products enumerated in Examples 33 and 34 in place of the dithiane used in Example 35.

10,11-dihydro-5-(3-diethylaminopropyl)-5,10-epoxy-5H-dibenzo[a,d]cycloheptene
 10,11-dihydro-5,10-epoxy-5-[3-(1-pyrrolidyl)-propyl]-5H-dibenzo[a,d]cycloheptene
 10,11-dihydro-5,10-epoxy-5-[3-(1-piperidyl)-propyl]-5H-dibenzo[a,d]cycloheptene
 10,11-dihydro-5,10-epoxy-5-[3-(1-ethyl-4-piperazinyl)-propyl]-5H-dibenzo[a,d]cycloheptene
 10,11-dihydro-5,10-epoxy-5-[3-(4-morpholinyl)-propyl]-5H-dibenzo[a,d]cycloheptene
 10,11-dihydro-5,10-epoxy-5-[3-(N-ethyl-N-methylamino)-propyl]-5H-dibenzo[a,d]cycloheptene

27

10,11-dihydro-5-(3-dimethylaminopropyl)-5,10-epoxy-
 3(7)-methylsulfonyl-5H-dibenzo[a,d]cycloheptene
 3(7)-chloro-10,11-dihydro-5-(3-dimethylaminopropyl)-
 5,10-epoxy-5H-dibenzo[a,d]cycloheptene
 10,11-dihydro-5-(3-dimethylaminopropyl)-3(7)-dimethyl-
 sulfamoyl-5,10-epoxy-5H-dibenzo[a,d]cycloheptene

EXAMPLE 37

Trans 10,11 - dihydro - 5 - (3-dimethylaminopropyl)-5,10-
 epoxy-11-hydroxyloxy-5H-dibenzo[a,d]cycloheptene

A solution of trans 10,11-dihydro-5-(3-dimethylaminopropyl) - 5,10 - epoxy-11-hydroxy-5H-dibenzo[a,d]cycloheptene, 310 mg. (0.001 mole), in 2 ml. of hexanoic anhydride is heated on the steam-bath for 18 hours. The solution is stirred with 75 ml. of water for 4 hours, then cooled in ice and made strongly basic with aqueous sodium hydroxide. The oily base is extracted into benzene and isolated by evaporation of the washed and dried benzene extract under reduced pressure. The residual oil is dissolved in absolute ether and treated with a 10% excess of maleic acid in absolute ethanol. The crystalline hydrogen maleate salt, M.P. 108-110° C., is obtained in a yield of 350 mg. (67%). Recrystallizations from ethanol-ether and isopropyl alcohol-ether afford an analytical sample, M.P. 109-110° C.

Analysis.—Calc'd for $C_{26}H_{33}NO_3 \cdot C_4H_4O_4$: C, 68.81; H, 7.12; N, 2.68. Found: C, 68.61; H, 7.07; N, 2.62.

EXAMPLE 38

10,11-dihydro-5-(3-dimethylaminopropyl)-5,10-epoxy-11-
 hydroxyimino-5H-dibenzo[a,d]cycloheptene

10,11 - dihydro-5-(3-dimethylaminopropyl)-5,10-epoxy-
 11-keto-5H-dibenzo[a,d]cycloheptene, 310 mg. (0.001
 mole), together with 80 mg. (0.00115 mole) of hydroxy-
 amine hydrochloride, 100 mg. (0.0012 mole) of sodium
 acetate, 1 ml. of water, and 9 ml. of methanol is heated
 to refluxing for 2 hours. Methanol is distilled under re-
 duced pressure and the residue dissolved in water. The
 solution is rendered alkaline and the precipitate collected,
 washed with water, and dried in *vacuo*. The yield of
 product, M.P. 197-204° C., is 300 mg. (93%). A sample
 purified by repeated crystallizations from 95% ethanol
 melts at 206-210° C.

Analysis.—Calc'd for $C_{20}H_{22}N_2O_2$: C, 74.51; H, 6.88;
 N, 6.89. Found: C, 74.37; H, 7.12; N, 8.56.

EXAMPLE 39

11-amino-10,11-dihydro-5-(3-dimethylaminopropyl)-5,10-
 epoxy-5H-dibenzo[a,d]cycloheptene

10,11 - dihydro-5-(3-dimethylaminopropyl)-5,10-epoxy-
 11-hydroxyimino-5H-dibenzo[a,d]cycloheptene, 400 mg.
 (0.00124 mole), is dissolved in 18 ml. of hot absolute
 ethanol and the solution is concentrated by distillation of
 12 ml. of ethanol. To the refluxing mixture, sodium
 spheres, 460 mg. (0.02 g., atom), are added as rapidly as
 possible over a 4 minute period. After another 15 minutes
 at reflux, 2 ml. of absolute ethanol are added and reflux-
 ing is continued until dissolution of the sodium is com-
 plete. The cooled mixture is diluted with an equal volume
 of water and ethanol is evaporated under reduced pres-
 sure. The oily product that separates from the residue is
 extracted into benzene. After washing with water, the
 benzene extract is evaporated to dryness under reduced
 pressure, leaving the oily base as the residue in a yield of
 275 mg. (72%).

The base may be converted to the dihydrogen maleate
 salt by treating an ethanolic solution with two equivalents
 of maleic acid dissolved in absolute ethanol. Dilution with
 absolute ether precipitates 11-amino-10,11-dihydro-5-(3-
 dimethylaminopropyl) - 5,10-epoxy-5H-dibenzo[a,d]cyclo-
 heptene dihydrogen dimaleate that melts at 163-167° C.,
 dec., after recrystallization from a mixture of absolute
 ethanol and absolute ether. Further purification affords a
 sample melting at 169-172° C., dec.

28

Analysis.—Calc'd for $C_{20}H_{24}N_2O \cdot 2C_4H_4O_4$: C, 62.21;
 H, 5.97; N, 5.18. Found: C, 61.90; H, 6.33; N, 5.46.

EXAMPLE 40

5 10,11-dihydro-11-dimethylamino-5-(3-dimethylamino-
 propyl)-5,10-epoxy-5H-dibenzo[a,d]cycloheptene

A mixture of 11-amino-10,11-dihydro-5-(3-dimethyl-
 aminopropyl) - 5,10-epoxy-5H-dibenzo[a,d]cycloheptene,
 308 mg. (0.001 mole), 37% formaldehyde, 180 mg.
 (0.0022 mole), and 98-100% formic acid, 250 mg. (0.005
 mole), is heated on a steam-bath for 8 hours. The solution
 is cooled, diluted with 10 ml. of 6 N hydrochloric acid
 and the excess formic acid and formaldehyde removed by
 distillation under reduced pressure. The 10,11-dihydro-11-
 15 dimethylamino - 5 - (3-dimethylaminopropyl)-5,10-epoxy-
 5-H-dibenzo[a,d]cycloheptene is obtained when the resid-
 ual aqueous acid solution is rendered alkaline.

EXAMPLE 41

20 Trans 10,11 - dihydro - 11-dimethylamino-5-(3-dimethyl-
 aminopropyl)-5,10-epoxy-5H-dibenzo[a,d]cycloheptene

A solution of trans 11-amino-10,11-dihydro-5-(3-di-
 25 methylaminopropyl) - 5,10 - epoxy-5H-dibenzo[a,d]cyclo-
 heptene, 310 mg. (0.001 mole), in 2 ml. of 98-100%
 formic acid and 0.2 ml. of 37% aqueous formaldehyde is
 allowed to stand at room temperature for 16 hours and
 then heated on the steam-bath for 4 hours. Solvents are
 distilled under reduced pressure and the residual syrup
 is dissolved in 10 ml. of water. The solution is rendered
 30 strongly alkaline and the oily base that separates is ex-
 tracted into benzene. After washing and drying the com-
 bined extracts, benzene is evaporated under reduced pres-
 sure leaving the product as a colorless oil weighing 280
 35 mg. The base is converted to the dihydrogen dimaleate by
 treating a solution in absolute ethanol with two equivalents
 of maleic acid dissolved in absolute ethanol. Dilution to
 incipient crystallization with ether precipitates the di-
 hydrogen dimaleate, M.P. 151-153° C., dec., in a yield
 40 of 400 mg. Recrystallization from isopropyl alcohol gives
 product, M.P. 150.5-151.5° C.

Analysis.—Calc'd for $C_{22}H_{28}N_2O \cdot 2C_4H_4O_4$: C, 63.37;
 H, 6.38; N, 4.93. Found: C, 63.56; H, 6.54; N, 4.96.

EXAMPLE 42

45 11-acetamido-10,11-dihydro-5-(3-dimethylaminopropyl)-
 5,10-epoxy-5H-dibenzo[a,d]cycloheptene

11 - amino-10,11-dihydro-5-(3-dimethylaminopropyl)-
 5,10-epoxy-5H-dibenzo[a,d]cycloheptene, 308 mg. (0.001
 50 mole), is dissolved in 3 ml. of dry pyridine, 0.5 ml. of
 acetic anhydride added, and the solution heated to re-
 fluxing for 30 minutes. After cooling, the solution is
 poured into 50 ml. of water and the mixture extracted
 55 with benzene. Evaporation of the washed and dried ben-
 zene extract leaves the product as the residue.

EXAMPLE 43

Trans 11 - acetamido-10,11-dihydro-5-(3-dimethylamino-
 60 propyl)-5,10-epoxy-5H-dibenzo[a,d]cycloheptene

A solution of trans 11-amino-10,11-dihydro-5-(3-di-
 methylaminopropyl) - 5,10-epoxy-5H-dibenzo[a,d]cyclo-
 heptene, 500 mg. (0.00162 mole), and acetic anhydride,
 65 1.17 g. (0.00162 mole) in 15 ml. of dry acetone is
 allowed to stand at room temperature for 5 days. Solvent
 is distilled under reduced pressure and the residual syrup
 is dissolved in water. The solution is rendered alkaline
 with concentrated ammonium hydroxide and the oily
 base that separates is extracted into chloroform. After
 70 washing and drying the combined extracts, chloroform
 is distilled under reduced pressure leaving the product
 as a yellow glass. Trituration with absolute ether gives
 crystalline product, M.P. 173-177° C., in a yield of 200
 mg. Repeated recrystallizations from acetonitrile raise
 75 the melting point to 179-181° C.

Analysis.—Calc'd for $C_{22}H_{26}N_2O_2$: C, 75.38; H, 7.48. Found: C, 75.30; H, 7.75.

EXAMPLE 44

Following the procedure of Example 42, the products enumerated below are obtained employing the anhydride designated below in place of the acetic anhydride used in Example 42.

Anhydride	Product
Propionic anhydride...	10,11-dihydro-5-(3-dimethylaminopropyl)-5,10-epoxy-11-propionamido-5H-dibenzo[a,d]cycloheptene.
Butyric anhydride...	11-butyramido-10,11-dihydro-5-(3-dimethylaminopropyl)-5,10-epoxy-5H-dibenzo[a,d]cycloheptene.

A solution of 11-acetamido-10,11-dihydro-5-(3-dimethylaminopropyl)-5,10-epoxy-5H-dibenzo[a,d]cycloheptene, 350 mg. (0.001 mole), in 10 ml. of absolute ether is added dropwise to a stirred suspension of 85 mg. (0.0022 mole) of lithium aluminum hydride in 5 ml. of absolute ether at room temperature and in an atmosphere of nitrogen. After stirring at reflux for 6 hours, the mixture is cooled in ice and hydrolyzed by the successive dropwise addition of 0.1 ml. of water, 0.1 ml. of 20% aqueous sodium hydroxide and 0.3 ml. of water. The ether solution is filtered from the granular precipitate, washed with water, and dried over anhydrous sodium sulfate. Evaporation of the ether leaves 10,11-dihydro-5-(3-dimethylaminopropyl)-11-ethylamino-5,10-epoxy-5H-dibenzo[a,d]cycloheptene as the residue.

EXAMPLE 46

Following the procedure of Example 45, the products enumerated below are obtained employing the dibenzocycloheptene designated below in place of the 11-acetamido-10,11-dihydro-5-(3-dimethylaminopropyl)-5,10-epoxy-5H-dibenzo[a,d]cycloheptene used in Example 45.

Product
10,11-dihydro-5-(3-dimethylaminopropyl)-5,10-epoxy-11-propionamido-5H-dibenzo[a,d]cycloheptene.
11-butyramido-10,11-dihydro-5-(3-dimethylaminopropyl)-5,10-epoxy-5H-dibenzo[a,d]cycloheptene.

EXAMPLE 47

5 - [3-(N-carbethoxy-N-methylamino)-propyl]-10,11-dihydro-5,10-epoxy-11-keto-5H-dibenzo[a,d]cycloheptene

A solution of 10,11-dihydro-5-(3-dimethylaminopropyl)-5,10-epoxy-11-keto-5H-dibenzo[a,d]cycloheptene, 620 mg. (0.002 mole), in 3 ml. of dry benzene is added dropwise to a stirred solution of 1.0 ml. of ethyl chloroformate in 3 ml. of dry benzene. After stirring for 1 hour at reflux, the mixture is cooled, diluted with benzene, and washed with 2 N hydrochloric acid, then with water. Evaporation of the benzene under reduced pressure leaves the product as the residue.

EXAMPLE 48

5 - [3-(N-carbethoxy-N-methylamino)-propyl]-10,11-dihydro-5,10-epoxy-11-hydroxyimino-5H-dibenzo[a,d]cycloheptene

5 - [3-(N-carbethoxy-N-methylamino)-propyl]-10,11-dihydro-5,10-epoxy-11-keto-5H-dibenzo[a,d]cycloheptene, 370 mg. (0.001 mole), together with 80 mg. (0.00115 mole) of hydroxylamine hydrochloride, 100 mg. (0.0012 mole) of sodium acetate, 1 ml. of water and 9 ml. of methanol, is heated to refluxing for 2 hours. Methanol is distilled under reduced pressure and the residue triturated with water. The product is obtained as the precipitate.

EXAMPLE 49

11 - amino - 5 - [3 - (N - carbethoxy-N-methylamino)-propyl] - 10,11 - dihydro - 5,10 - epoxy - 5H - dibenzo [a,d]cycloheptene

5 The oxime obtained in Example 48, 385 mg. (0.001 mole), is dissolved in 6 ml. of hot absolute ethanol. To the refluxing mixture, sodium spheres, 460 mg. (0.02 g., atom), are added as rapidly as possible. After another 15 minutes at reflux, 2 ml. of absolute ethanol are added and refluxing is continued until dissolution of the sodium is complete. The cooled mixture is diluted with an equal volume of water and ethanol is evaporated under reduced pressure. The residual mixture is extracted with benzene and the product obtained by evaporation of the washed and dried benzene extract.

EXAMPLE 50

5 - [3 - (N - carbethoxy-N-methylamino)-propyl]-10,11-dihydro-11-dimethylamino-5,10-epoxy-5H-dibenzo [a,d]cycloheptene

11 - amino - 5 - [3-(N-carbethoxy-N-methylamino)-propyl] - 10,11 - dihydro - 5,10-epoxy-5H-dibenzo[a,d]cycloheptene, 365 mg. (0.001 mole), 37% formaldehyde, 80 mg. (0.0022 mole), and 98-100% formic acid, 250 mg. (0.005 mole), are heated on a steam-bath for 8 hours. After cooling, the solution is diluted with 10 ml. of 6 N hydrochloric acid and the excess formic acid and formaldehyde removed by distillation under reduced pressure. The product is obtained when the residual aqueous acid solution is rendered alkaline.

EXAMPLE 51

10,11 - dihydro - 11 - dimethylamino-5,10-epoxy-5-(3-methylaminopropyl)-5H-dibenzo[a,d]cycloheptene

A solution of 5-[3-(N-carbethoxy-N-methylamino)-propyl]-10,11-dihydro-11-dimethylamino-5,10-epoxy-5H-dibenzo[a,d]cycloheptene, 395 mg. (0.001 mole), and 40 potassium hydroxide, 300 mg. (0.00535 mole), in 6 ml.

Product
10,11-dihydro-5-(d-dimethylaminopropyl)-5,10-epoxy-11-propylamino-5H-dibenzo[a,d]cycloheptene.
11-butyramino-10,11-dihydro-5-(3-dimethylaminopropyl)-5,10-epoxy-5H-dibenzo[a,d]cycloheptene.

of n-butyl alcohol is stirred and heated to refluxing in a nitrogen atmosphere for 8 hours. The solvent is evaporated under reduced pressure and the residue partitioned between benzene and water. Evaporation of the washed and dried benzene extract leaves the product as the residue.

EXAMPLE 52

10,11-dihydro-5-(3-dimethylaminopropyl)-5,10-epoxy-11-hydroxy-11-methyl-5H-dibenzo[a,d]cycloheptene

Magnesium turnings, 145 mg. (0.06 g., atom), a crystal of iodine, and 25 ml. of tetrahydrofuran are placed in a 50 ml. reaction flask fitted with a stirrer, reflux condenser and gas inlet tube. The apparatus is flushed with dry nitrogen and protected from atmospheric moisture by means of a drying tube. The reaction is initiated with a drop of methyl iodide and then methyl chloride is introduced below the surface of the stirred mixture at room temperature. Passage of the gas is continued until all of the magnesium dissolves. The solution of the Grignard reagent then is added dropwise to a stirred solution of 900 mg. (0.0029 mole) of 10,11-dihydro-5-(3-dimethylaminopropyl)-5,10-epoxy-11-keto-5H-dibenzo[a,d]cycloheptene in 25 ml. of tetrahydrofuran maintained in a nitrogen atmosphere and cooled in an ice-bath. The mixture is stirred at room temperature for 45 minutes and the bulk of the tetrahydrofuran is evaporated below 50° C. under reduced pressure. The

31

residue is dissolved in benzene and hydrolyzed by the dropwise addition of 10 ml. of water. The benzene layer is separated by decantation and the gelatinous precipitate washed with several portions of benzene. After washing with water, the combined benzene solutions are extracted with three 25 ml. portions of 0.5 M citric acid. The acid extract is rendered alkaline and the oily base extracted into benzene. The washed and dried benzene extract is evaporated under reduced pressure, leaving the product as an oily residue that solidifies on trituration with absolute ether. The yield of product melting at 108-110° C. is 700 mg. (75%). The base may be converted to the hydrogen maleate salt by treating an ethanolic solution with a 10% excess of maleic acid dissolved in absolute ethanol. Dilution with absolute ether precipitates 10,11-dihydro-5-(3-dimethylaminopropyl) - 5,10-epoxy-11-hydroxy-11-methyl-5H-dibenzo[a,d]cycloheptene hydrogen maleate, M.P. 182-184° C. The melting point is unchanged by further recrystallization.

Analysis.—Cal'd for $C_{21}H_{25}NO_2 \cdot C_4H_4O_4$: C, 68.32; H, 6.65; N, 3.19. Found: C, 67.89; H, 6.62; N, 3.30.

EXAMPLE 53

10,11-dihydro-5-(3-dimethylaminopropyl)-5,10-epoxy-11-methoxyimino-5H-dibenzo[a,d]cycloheptene

10,11 - dihydro - 5 - (3 - dimethylaminopropyl)-5,10-epoxy - 11 - keto-5H-dibenzo[a,d]cycloheptene, 1.5 g. (0.005 mole), together with 500 mg. (0.006 mole) of methoxyamine hydrochloride, 825 mg. (0.0061 mole) of sodium acetate trihydrate, 5 ml. of water, and 45 ml. of methanol is heated to refluxing for 19 hours. Methanol is distilled under reduced pressure and the residue dissolved in water. The solution is rendered alkaline and the oily base that separates is extracted into benzene. After washing and drying the combined extracts, benzene is evaporated under reduced pressure leaving the product as an oil weighing 1.55 g. A sample of the base from a previous experiment is converted to the hydrogen oxalate salt by treating an ethanolic solution with one equivalent of oxalic acid dissolved in absolute ethanol. Dilution with ether precipitates 10,11-dihydro-5-(3-dimethylaminopropyl) - 5,10 - epoxy - 11 - methoxyimino-5H - dibenzo[a,d]cycloheptene hydrogen oxalate as a white crystalline solid, M.P. dec. 159.5-160.5° C. Repeated recrystallizations from absolute ethanol give product, M.P. dec. 162.5-163.5° C.

Analysis.—Cal'd for $C_{21}H_{24}N_2O_2 \cdot C_2H_2O_4$: C, 64.77; H, 6.15; N, 6.57. Found: C, 64.75; H, 6.11; N, 6.57.

EXAMPLE 54

11-acetoxyimino-10,11-dihydro-5-(3-dimethylaminopropyl)-5,10-epoxy-5H-dibenzo[a,d]cycloheptene

A solution of 10,11-dihydro-5-(3-dimethylaminopropyl) - 5,10 - epoxy - 11 - hydroxyimino-5H-dibenzo[a,d]cycloheptene, 645 mg. (0.002 mole), in 4 ml. of acetic anhydride is heated on the steam-bath for 1½ hours and then allowed to stand at room temperature for 2 days. Solvent is distilled under reduced pressure and the residual syrup dissolved in 10 ml. of water. After repeated extraction with benzene, the aqueous solution is cooled in ice, rendered strongly alkaline, and the oily base that separates is extracted into benzene. After washing and drying the combined extracts, benzene is evaporated under reduced pressure, leaving the product as an oily solid weighing 650 mg. Recrystallization from ether-petroleum ether gives product, M.P. 129-132° C., and further recrystallizations from ether-petroleum ether raise the melting point to 133-134° C.

Analysis.—Cal'd for $C_{22}H_{24}N_2O_3$: C, 72.50; H, 6.64; N, 7.69. Found: C, 72.31; H, 6.81; N, 7.64.

EXAMPLE 55

Trans 10,11 - dihydro-5-(3-dimethylaminopropyl)-5,10-epoxy - 11-methanesulfonamido-5H-dibenzo[a,d]cycloheptene

32

Trans 11 - amino-10,11-dihydro-5-(3-dimethylaminopropyl) - 5,10-epoxy-5H-dibenzo[a,d]cycloheptene, 308 mg. (0.001 mole), and 2 ml. of dry pyridine are stirred and cooled in an ice-bath. Methanesulfonyl chloride, 0.1 ml., is added dropwise. Stirring is continued for 5 hours at room temperature and for 5 minutes on the steam-bath and the solution then is poured into 40 ml. of water. The aqueous solution is adjusted to pH 8 with 5% aqueous sodium hydroxide and the precipitate is collected, washed with water, and dried in a vacuum oven at 60°. The product, M.P. 207-210° C., weighs 275 mg. Repeated recrystallizations from 95% ethanol raise the melting point to 210-211° C.

Analysis.—Cal'd for $C_{21}H_{26}N_2O_3S$: C, 65.26; H, 6.78; N, 7.25. Found: C, 65.17; H, 6.95; N, 7.06.

EXAMPLE 56

Trans 11-amino-10,11-dihydro-5,10-epoxy-5-(3-methylaminopropyl)-5H-dibenzo[a,d]cycloheptene

A solution of 10,11-dihydro-5,10-epoxy-5-(3-methylaminopropyl) - 11-hydroxyimino-5H-dibenzo[a,d]cycloheptene, 650 mg. (0.0021 mole), in 50 ml. absolute methanol-5 ml. concentrated ammonium hydroxide is shaken with hydrogen at atmospheric pressure in the presence of 300 mg. of 5% palladium on charcoal until the uptake of hydrogen is complete. The mixture is filtered through a mat of diatomaceous earth and the filtrate evaporated to dryness under reduced pressure. The residual yellow oily base weighs 600 mg. and is converted to the dihydrogen dimaleate by treating a solution of the base in isopropyl alcohol with two equivalents of maleic acid dissolved in isopropyl alcohol. The dihydrogen dimaleate is obtained as white crystals, M.P. 173-175° C. in a yield of 800 mg. Repeated recrystallizations from isopropyl alcohol give product, M.P. 187-188° C.

Analysis.—Calc'd for $C_{19}H_{22}N_2O_2 \cdot C_4H_4O_4$: C, 61.59; H, 5.74; N, 5.32. Found: C, 61.86; H, 6.07; N, 5.07.

EXAMPLE 57

40 10,11-dihydro-5,10-epoxy-11-hydroxyimino-5-(3-methylaminopropyl)-5H-dibenzo[a,d]cycloheptene

By replacing the 10,11-dihydro-5-(3-dimethylaminopropyl) - 5,10 - epoxy - 11 - keto-5H-dibenzo[a,d]cycloheptene used in Example 38 with an equimolecular amount of 10,11-dihydro-5,10-epoxy-11-keto-5-(3-methylaminopropyl)-5H-dibenzo[a,d]cycloheptene and following substantially the same procedure described in Example 38, there is obtained 10,11-dihydro-5,10-epoxy-11-hydroxyimino - 5 - (3-methylaminopropyl)-5H-dibenzo[a,d]cycloheptene. The yield of white crystalline base, M.P. 210-214° C. dec., is 36%. Recrystallizations from absolute ethanol raise the melting point to 214-216° C. dec.

Analysis.—Calc'd for $C_{19}H_{20}N_2O_2$: C, 74.00; H, 6.54; N, 9.09. Found: C, 73.78; H, 6.42; N, 8.84.

EXAMPLE 58

10,11-dihydro-5,10-epoxy-11-keto-5-(3-methylaminopropyl)-5H-dibenzo[a,d]cycloheptene

60 By replacing the trans 10,11-dihydro-5-(3-dimethylaminopropyl) - 5,10-epoxy-11-hydroxy-5H-dibenzo[a,d]-cycloheptene used in Example 30 with an equimolecular amount of trans 10,11-dihydro-5,10-epoxy-11-hydroxy-5-(3 - methylaminopropyl) - 5H-dibenzo[a,d]cycloheptene and following substantially the same procedure described in Example 30, there is obtained 10,11-dihydro-5,10-epoxy - 11 - keto-5-(3-methylaminopropyl)-5H-dibenzo[a,d]cycloheptene. The yield of yellow oily base is quantitative. The base is converted to the hydrogen maleate by dissolving it in absolute ethanol and adding a solution of a slight excess of maleic acid in absolute ethanol. Dilution to incipient crystallization with absolute ether precipitates the hydrogen maleate, M.P. 150-151° C. in a yield of 67%. The melting point is unchanged by recrystallization from absolute ethanol-absolute ether.

Analysis.—Calc'd for $C_{19}H_{19}NO_2 \cdot C_4H_4O_4$: C, 67.46; H, 5.66; N, 3.42. Found: C, 67.07; H, 5.70; N, 3.48.

EXAMPLE 59

Trans 11 - acetoxy - 10,11-dihydro-5-(3-methylamino-propyl)-5,10-epoxy-5H-dibenzo[a,d]cycloheptene

A solution of trans 10,11-dihydro-5,10-epoxy-11-hydroxy - 5 - (3 - methylaminopropyl)-5H-dibenzo[a,d]cycloheptene hydrogen maleate, 1.0 g. (0.00243 mole) in 5 ml. of glacial acetic acid-5 ml. of 6 N hydrochloric acid is stirred and cooled in an ice-salt bath. Acetyl chloride, 50 ml. is added rapidly dropwise. Stirring is continued for 1 hour in the cold and the solution then is concentrated below 25° to a volume of 15-20 ml. under reduced pressure. Dilution of the residual solution with 50 ml. of absolute ether precipitates the product hydrochloride, M.P. 247-249° C. dec., in a yield of 850 mg. Repeated recrystallizations from absolute ethanol give product, M.P. 254-255° C. dec.

Analysis.—Calc'd for $C_{21}H_{23}NO_3 \cdot HCl$: C, 67.47; H, 6.47; N, 3.75. Found: C, 67.70; H, 6.79; N, 3.90.

EXAMPLE 60

Trans 11-benzoyloxy-10,11-dihydro-5-(3-dimethylamino-propyl)-5,10-epoxy-5H-dibenzo[a,d]cycloheptene

Trans 10,11-dihydro-5-(3-dimethylaminopropyl)-5,10-epoxy-11-hydroxy-5H-dibenzo[a,d]cycloheptene, 618 mg. (0.002 mole), and 3 ml. of dry pyridine are stirred and cooled in an ice-bath. Benzoyl chloride, 310 mg. (0.0022 mole) is added dropwise. Stirring is continued for 1 hour in the cold and the mixture then is allowed to stand 24 hours at room temperature. After heating for 45 minutes on the steam bath, the mixture is poured into 50 ml. of water. This solution is cooled in an ice-bath, rendered strongly alkaline, and the oily base that separates is extracted into benzene. After washing the combined extracts with water, the benzene is evaporated leaving the product as a yellow oil in a yield of 800 mg. The base is converted to the hydrochloride by dissolving it in 5 ml. of absolute ethanol and adding 0.35 ml. of 5.92 N ethanolic hydrogen chloride. Dilution to incipient crystallization with 25 ml. of absolute ether precipitates trans 11 - benzoyloxy - 10,11 - dihydro-5-(3-dimethylamino-propyl) - 5,10-epoxy-5H-dibenzo[a,d]cycloheptene hydrochloride, M.P. 253-255° C. dec., in a yield of 790 mg. Recrystallizations from isopropyl alcohol and from absolute alcohol-absolute ether raise the melting point to 259.5-260.5° C. dec.

Analysis.—Calc'd for $C_{27}H_{27}NO_3 \cdot HCl$: C, 72.06; H, 6.27; N, 3.11. Found: C, 71.86; H, 6.64; N, 2.89.

EXAMPLE 61

Trans 10,11 - dihydro - 5 - (3 - dimethylaminopropyl)-5,10 - epoxy - 11 - hydroxy - 5H - dibenzo[a,d]cycloheptene N-oxide

Trans 10,11 - dihydro - 5 - (3 - dimethylaminopropyl)-5,10 - epoxy - 11 - hydroxy - 5H - dibenzo[a,d]cycloheptene, 2.06 g. (0.0067 mole), and 20 ml. of absolute methanol are stirred and cooled in an ice-bath. Hydrogen peroxide, 2.3 g. of 30%, is added dropwise. Stirring is continued for 1 hour in the cold and for 19 hours at room temperature and the mixture then is allowed to stand for 24 hours at room temperature. After cooling in an ice-bath, the mixture is treated with a suspension of 100 mg. of 5% palladium on charcoal in 1 ml. of water and stirred at room temperature for 2½ hours when a test for peroxide is negative. After filtration through a mat of diatomaceous earth, the filtrate is evaporated below 40° C. under reduced pressure. The residual colorless glass weighs 2.3 g. after drying for 3 days in a vacuum desiccator over phosphorus pentoxide. The base is converted to the hydrogen maleate by dissolving it in 20 ml. of cold

absolute ethanol and adding a solution of 860 mg. of maleic acid in 5 ml. of absolute ethanol. Dilution to incipient crystallization with 25 ml. of absolute ether precipitates the hydrogen maleate, M.P. 151-152° C. dec., in a yield of 2.6 g. Recrystallization from cold absolute methanol-absolute ether gives product, M.P. 155-156° C. dec.

Analysis.—Calc'd for $C_{20}H_{23}NO_3 \cdot C_4H_4O_4$: C, 65.29; H, 6.16; N, 3.17. Found: C, 65.37; H, 6.16; N, 3.13.

EXAMPLE 62

Trans 10,11 - dihydro - 5 - [3 - N - carbethoxy - N-methylamino)propyl] - 5,10 - epoxy - 11 - hydroxy-5H-dibenzo[a,d]cycloheptene

Trans 10,1 - dihydro - 5 - (3 - dimethylaminopropyl)-5,10 - epoxy - 11 - hydroxy - 5H - dibenzo[a,d]cycloheptene, 3.1 g. (0.01 mole), is added in portions over 30 minutes with stirring to 100 ml. of ethyl chloroformate. The mixture is stirred and heated to refluxing for 30 hours until a clear solution is obtained. Solvent is distilled under reduced pressure and the residual oil dissolved in benzene. The benzene solution is washed with water, 0.5 M citric acid, and water, dried by filtration through anhydrous sodium sulfate, and evaporated under reduced pressure. The trans 10,11 - dihydro - 5 - [3-(N-carbethoxy-N-methylamino)propyl] - 5,10 - epoxy - 11 - hydroxy - 5H-dibenzo[a,d]cycloheptene is obtained as a viscous, yellow oil weighing 3.6 g.

EXAMPLE 63

Trans 10,11 - dihydro - 5,10 - epoxy - 11 - hydroxy - 5 - (3 - methylaminopropyl) - 5H - dibenzo[a,d]cycloheptene

Trans 10,11 - dihydro - 5 - [3 - (N - carbethoxy - N-methylamino)propyl] - 5,10 - epoxy - 11 - hydroxy - 5H-dibenzo[a,d]cycloheptene, 2.76 g. (0.0075 mole), and 10 g. (0.175 mole) of potassium hydroxide are stirred and heated to refluxing in 50 ml. of n-butyl alcohol for 16 hours. Solvent is distilled under reduced pressure and the residue partitioned between benzene and water. The combined benzene extracts are washed with water and extracted with 0.5 M citric acid. The aqueous acid solution is rendered strongly alkaline and the oily base that separates is extracted into benzene. Evaporation of the washed and dried benzene extract leaves the crude product as a yellow oil weighing 1.2 g. The base is converted to the hydrogen maleate by treating a solution in isopropyl alcohol with a solution of 520 mg. of maleic acid in isopropyl alcohol. Dilution to incipient crystallization with absolute ether precipitates the hydrogen maleate, M.P. 130-138° C., in a yield of 1.3 g. Recrystallization from isopropyl alcohol-absolute ether gives product M.P. 152-154° C.

Analysis.—Calc'd for $C_{19}H_{21}NO_2 \cdot C_4H_4O_4$: C, 67.14; H, 6.12; N, 3.40. Found: C, 66.88; H, 6.40; N, 3.60.

EXAMPLE 64

10,11-dihydro-5-(3-dimethylaminopropyl)-5,10-epoxy-11-hydrazone-5H-dibenzo[a,d]cycloheptene

10,11 - dihydro - 5 - (3 - dimethylaminopropyl) - 5,10-epoxy - 11 - keto - 5H - dibenzo[a,d]cycloheptene, 620 mg. (0.002 mole), together with 0.5 ml. of 64% hydrazine, 2 ml. of triethylamine, and 6 ml. of absolute ethanol is heated to refluxing for 2½ hours. The cooled solution is diluted with water and the oily base extracted into benzene. The washed benzene extract is evaporated under reduced pressure, leaving the oily base as the residue in a yield of 500 mg. Trituration with absolute ether gives the product as an oily solid, M.P. dec. 100-120° C. Repeated recrystallizations from cyclohexane afford an analytical sample, M.P. dec. 131-133° C.

Analysis.—Calc'd for $C_{20}H_{23}N_3O$: C, 74.74; H, 7.21; N, 13.07. Found: C, 74.65; H, 7.42; N, 12.91.

EXAMPLE 65

11 - acetoxy - 10,11 - dihydro - 5 - (3 - dimethylaminopropyl) - 5,10 - epoxy - 11 - methyl - 5H - dibenzo [a,d] cycloheptene

By replacing the cis 10,11 - dihydro - 5 - (3 - dimethylaminopropyl) - 5,10 - epoxy - 11 - hydroxy - 5H-dibenzo [a,d]cycloheptene used in Example 14 with an equimolecular amount of 10,11 - dihydro - 5 - (3 - dimethylaminopropyl) - 5,10 - epoxy - 11 - hydroxy - 11 - methyl-5H-dibenzo[a,d]cycloheptene and following substantially the same procedure described in Example 14, there is obtained 11 - acetoxy - 10,11 - dihydro - 5 - (3 - dimethylaminopropyl) - 5,10 - epoxy - 11 - methyl - 5H - dibenzo [a,d]cycloheptene. The yield of white crystalline base, M.P. 108-122° C., is 49%. An analytical sample melts at 122-126° C. after recrystallization from a mixture of ether and petroleum ether and sublimation at 115° C. and 0.05 mm.

Analysis.—Calc'd for $C_{23}H_{27}NO_3$: C, 75.59; H, 7.45; N, 3.83. Found: C, 75.72; H, 7.45; N, 3.77.

EXAMPLE 66

5 - [3 - (N - carbethoxy - N - methylamino) - propyl] - 10,11 - dihydro - 5,10 - epoxy - 11 - hydroxy - 11 - methyl-5H-dibenzo[a,d]cycloheptene

By replacing the trans 11 - acetoxy - 10,11 - dihydro - 5 - (3 - dimethylaminopropyl) - 5,10 - epoxy - 5H - dibenzo[a,d]cycloheptene used in Example 25 with an equimolecular amount of 10,11 - dihydro - 5 - (3 - dimethylaminopropyl) - 5,10 - epoxy - 11 - hydroxy - 11 - methyl-5H - dibenzo[a,d]cycloheptene and following substantially the same procedure described in Example 25, there is obtained 5 - [3 - (N - carbethoxy - N - methylamino) propyl] - 10,11 - dihydro - 5,10 - epoxy - 11 - hydroxy - 11 - methyl - 5H - dibenzo[a,d]cycloheptene. The yield of yellow oily urethane is 95%.

EXAMPLE 67

10,11-dihydro-5,10-epoxy-11-hydroxy-11-methyl-5-(3-methylaminopropyl)-5H-dibenzo[a,d]cycloheptene

A solution of 5-[3-(N-carbethoxy-N-methylamino) propyl] - 10,11 - dihydro - 5,10 - epoxy - 11 - hydroxy - 11 - methyl - 5H - dibenzo[a,d]cycloheptene (800 mg., 0.00216 mole) and potassium hydroxide (8.0 g., 0.014 mole) in 40 ml. of n-butyl alcohol is stirred and heated to refluxing in a nitrogen atmosphere for 12 hours. The solvent is evaporated under reduced pressure and the residue partitioned between benzene and water. After re-extraction of the aqueous phase, the combined benzene extracts are washed with water and then extracted with three portions of 0.5 M citric acid. The citric acid extract is rendered alkaline with sodium hydroxide and the oily base extracted into benzene. The washed and dried benzene extract is evaporated to dryness under reduced pressure, leaving the crystalline base as the residue in a yield of 400 mg. (60%). Sublimation at 120-128° C. and 0.02 mm. gives an analytical sample, M.P. 156.5-158.5° C.

Analysis.—Calc'd for $C_{20}H_{23}NO_2$: C, 77.64; H, 7.49; N, 4.53. Found: C, 77.90; H, 7.36; N, 4.65.

EXAMPLE 68

10,11 - dihydro - 5 - [3 - (N - carbethoxy - N - methylamino)propyl] - 5,10 - epoxy - 5H - dibenzo[a,d]cycloheptene

A solution of 2.1 g. (0.00717 mole) of 10,11-dihydro - 5 - (3 - dimethylaminopropyl) - 5,10 - epoxy - 5H - dibenzo[a,d]cycloheptene in 11.5 ml. of dry benzene is added dropwise to a stirred solution of 3.05 ml. of ethyl chloroformate in 7.6 ml. of dry benzene. An oil separates and the mixture is stirred and heated to refluxing for 16-18 hrs. Benzene is added and the solution is washed with three portions each of water, 0.5 M citric acid, and water. Distillation of the benzene under reduced pressure

leaves the product as the oily residue in a yield of 2.3 g. (91%).

EXAMPLE 69

10,11-dihydro-5,10-epoxy-5-(3-methylaminopropyl)-5H-dibenzo[a,d]cycloheptene

10,11 - dihydro - 5 - [3 - (N - carbethoxy - N - methylamino)propyl] - 5,10 - epoxy - 5H - dibenzo[a,d]cycloheptene, 2.3 g. (0.00655 mole), together with 25 g. of potassium hydroxide and 125 ml. of n-butyl alcohol are stirred and heated to refluxing in an atmosphere of nitrogen for 12 hr. Solvent is distilled under reduced pressure and the residue partitioned between benzene and water. The benzene layer is separated, washed with water, and extracted with 0.5 M citric acid. The acid extract is rendered strongly alkaline with sodium hydroxide and the oily base is extracted into benzene. Evaporation of the washed and dried benzene extract under reduced pressure leaves the product as the oily residue weighing 1.5 g. (82%). The base may be converted to the hydrogen oxalate by treating an ethanolic solution with a 10% excess of oxalic acid in absolute ethanol. The hydrogen oxalate precipitates in white crystals, M.P. 144-148° C. Repeated recrystallizations from mixtures of absolute ethanol and absolute ether afford an analytical sample, M.P. 150-151.5° C.

Analysis.—Calc'd for $C_{19}H_{21}NO \cdot C_2H_2O_4$: C, 68.28; H, 6.28; N, 3.79. Found: C, 68.11; H, 6.41; N, 3.67.

EXAMPLE 70

Trans (-) 10,11-dihydro-5-(3-dimethylaminopropyl)-5,10-epoxy-11-hydroxy-5H-dibenzo[a,d]cycloheptene

35 Racemic trans 10,11-dihydro-5-(3-dimethylaminopropyl)5,10-epoxy-11-hydroxy-5H-dibenzo[a,d]cycloheptene, 12.36 g. (0.04 mole), is dissolved in 200 ml. of boiling absolute ethanol and treated with a solution of 6.0 g. (0.04 mole) of (-) tartaric acid in 150 ml. of warm absolute ethanol. The (-) tartrate crystallizes as the solution cools and several crops are collected until no further precipitation occurs. The ethanolic mother liquor then is evaporated to dryness under reduced pressure and the residual syrup is dissolved in 100 ml. of water. The solution is rendered strongly alkaline with aqueous sodium hydroxide and the oily base extracted into benzene. Evaporation of the washed and dried benzene extract under reduced pressure leaves the crystalline (-) base weighing 1.52 g. Recrystallization from benzene hexane affords 1.35 g. of product, M.P. 154-157° C.

40 The (-) base is dissolved in 20 ml. of boiling absolute ethanol and treated with a solution of 655 mg. (0.00437 mole) of (+) tartaric acid in 10 ml. of warm absolute ethanol. The (+) tartrate separates in white crystals, M.P. 237-239° C. dec.; yield, 1.40 g. Three recrystallizations from 95% ethanol give product of constant specific rotation;

$$[\alpha]_{D}^{25} - 271.0 \pm 5^{\circ}$$

45 50 M.P. 238-239° C. dec.

Analysis.—Calc'd for $C_{20}H_{23}NO_2 \cdot \frac{1}{2}C_4H_6O_6$: C, 68.58; H, 6.82. Found: C, 68.44; H, 6.96.

55 The (+) tartrate, 700 mg. (0.00182 mole), is dissolved in 20 ml. water, the solution made strongly basic with 5% aqueous sodium hydroxide, and the oily base extracted into benzene. Evaporation of the washed and dried benzene extract under reduced pressure leaves the crystalline (-) base. Recrystallization from a mixture of benzene and hexane gives 476 mg. of product, M.P. 156-158° C.,

$$[\alpha]_{D}^{25} - 1100^{\circ} (\pm 5 \text{ to } 10\%)$$

70 75 *Analysis.*—Calc'd for $C_{20}H_{23}NO_2$: C, 77.64; H, 7.49; N, 4.53. Found: C, 77.65; H, 7.39; N, 4.63.

37

EXAMPLE 71

Trans (+) 10,11-dihydro-5-(3-dimethylaminopropyl)-5, 10-epoxy-11-hydroxy-5H-dibenzo[a,d]cycloheptene

Racemic trans 10,11-dihydro - 5 - (3 - dimethylamino- propyl) - 5,10 - epoxy - 11 - hydroxy - 5H - dibenzo[a,d] cycloheptene, 12.36 g. (0.04 mole), is dissolved in 200 ml. of boiling absolute ethanol and treated with a solution of 6.0 g. (0.04 mole) of (+) tartaric acid in 150 ml. of warm absolute ethanol. After the addition of 50 ml. of 95% ethanol, the (+) tartrate crystallizes as the solution cools and is collected after several days at room temperature. The ethanolic mother liquor then is evaporated to dryness under reduced pressure and the residual syrup is dissolved in 100 ml. of water. The solution is rendered strongly alkaline with aqueous sodium hydroxide and the oily base extracted into benzene. Evaporation of the washed and dried benzene extract under reduced pressure leaves the crystalline (+) base weighing 1.9 g., M.P. 155-157° C.

The base is dissolved in 20 ml. of boiling 95% ethanol and treated with a solution of 925 mg. (0.00615 mole) of (-) tartaric acid in 5 ml. of warm 95% ethanol. The (-) tartaric separates in white crystals, M.P. 238-239° C. dec.; yield, 0.85 g. A second crop of 0.75 g., M.P. 238-239° C. dec., is obtained from the mother liquor and combined with the first crop. Three recrystallizations from 95% ethanol give product of constant specific rotation;

$$[\alpha]_{D}^{25} + 290^{\circ} \pm 5^{\circ}$$

M.P. 238-239° C. dec.

Analysis.—Calc'd for $C_{20}H_{23}NO_2 \cdot \frac{1}{2}C_4H_6O_6$: C, 68.58; H, 6.82. Found: C, 68.33; H, 6.71.

The (-) tartrate, 950 mg. (0.00247 mole), is dissolved in 20 ml. of water, the solution made strongly basic with 5% aqueous sodium hydroxide, and the oily base extracted into benzene. Evaporation of the washed and dried benzene extract under reduced pressure leaves the crystalline (+) base. Recrystallization from a mixture of benzene and hexane gives 556 mg. of product, M.P. 156-158° C.,

$$[\alpha]_{D}^{25} + 1100^{\circ} (\pm 5 \text{ to } 10\%)$$

Analysis.—Calc'd for $C_{20}H_{23}NO_2$: C, 77.64; H, 7.49; N, 4.53. Found: C, 77.71; H, 7.42; N, 4.63.

What is claimed is:

1. A compound of the formula

or a non-toxic salt thereof; wherein Z is the radical H, OH, OY, NH₂, NH_{SO₂}R or

R is lower alkyl or the radical

wherein B is hydrogen, halogen, trifluoromethyl, lower alkyl or lower alkoxy, and n is a whole number of from 0 to 3; R'' is hydrogen or lower alkyl; R' and R'' are each lower alkyl or together form with the nitrogen atom attached thereto the radical 1-piperidyl, 1-pyrrolidyl, 4-morpholinyl or 1-loweralkyl-4-piperazinyl; and X and X' are each hydrogen, lower alkyl, lower alkenyl, halogen, trifluoromethyl, hydroxy, lower alkoxy, mercapto, lower alkylmercapto, loweralkylsulfonyl, sulfamoyl, loweralkylsulfamoyl or diloweralkylsulfamoyl.

38

alkyl; Y is alkanoyl or from 1 to 18 carbon atoms, or the radical

wherein B and n are as defined; A is hydrogen when Z is H, OH, OY, NH₂, NH_{SO₂}R or

or the radical R'' when Z is OH or OY, or Z and A together form the radicals =NOR°, =NOY or =NNH₂; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

2. A compound of the formula

or a non-toxic salt thereof; wherein Z is the radical H, OH, OY, NH₂, NH_{SO₂}R or

R is lower alkyl or the radical

wherein B is hydrogen, halogen, trifluoromethyl, lower alkyl or lower alkoxy and n is a whole number of from 0 to 3; R'' is hydrogen or lower alkyl, R' is lower alkyl; R''' is lower alkyl; Y is alkanoyl of from 1 to 18 carbon atoms, or the radical

wherein B and n are as defined; A is hydrogen when Z is H, OH, OY, NH₂, NH_{SO₂}R or

or the radical R''' when Z is OH or OY, or Z and A together form the radicals =NOR°, =NOY or =NNH₂; and X and X' are each hydrogen, lower alkyl, lower alkenyl, halogen, trifluoromethyl, hydroxy, lower alkoxy, mercapto, lower alkylmercapto, loweralkylsulfonyl, sulfamoyl, loweralkylsulfamoyl or diloweralkylsulfamoyl.

3. A compound of the formula

or a non-toxic salt thereof; wherein R' and R'' are each lower alkyl or together form with the nitrogen atom attached thereto the radical 1-piperidyl, 1-pyrrolidyl, 4-morpholinyl or 1-loweralkyl-4-piperazinyl; and X and X' are each hydrogen, lower alkyl, lower alkenyl, halogen, trifluoromethyl, hydroxy, lower alkoxy, mercapto, lower alkylmercapto, loweralkylsulfonyl, sulfamoyl, loweralkylsulfamoyl and diloweralkylsulfamoyl.

4. A compound of the formula

or a non-toxic salt thereof; wherein R' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

5. A compound of the formula

or a non-toxic salt thereof; wherein R' and R'' are each lower alkyl or together form with the nitrogen atom attached thereto the radical 1-piperidyl, 1-pyrrolidyl, 4-morpholinyl or 1-loweralkyl-4-piperazinyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

6. A compound of the formula

or a non-toxic salt thereof; wherein R' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

7. A compound of the formula

or a non-toxic salt thereof; wherein Y is of from 1 to 18 carbon atoms, or the radical

wherein B is hydrogen, halogen, trifluoromethyl, lower alkyl or lower alkoxy and n is a whole number of from 0 to 3; R' and R'' are each lower alkyl or together form with the nitrogen atom attached thereto the radical 1-piperidyl, 1-pyrrolidyl, 4-morpholinyl or 1-loweralkyl-4-piperazinyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

8. A compound of the formula

or a non-toxic salt thereof; wherein R' is lower alkyl; Y is alkanoyl of from 1 to 18 carbon atoms, or the radical

wherein B is hydrogen, halogen, trifluoromethyl, lower alkyl or lower alkoxy and n is a whole number of from 0 to 3; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

9. A compound of the formula

30

or a non-toxic salt thereof; wherein R' and R'' are each lower alkyl or together form with the nitrogen atom attached thereto the radical 1-piperidyl, 1-pyrrolidyl, 4-morpholinyl or 1-loweralkyl-4-piperazinyl; R° is hydrogen or lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

10. A compound of the formula

45

or a non-toxic salt thereof; wherein R° is hydrogen or lower alkyl; R' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

55

11. A compound of the formula

60

or a non-toxic salt thereof; wherein R' and R'' are each lower alkyl or together form with the nitrogen atom attached thereto the radical 1-piperidyl, 1-pyrrolidyl, 4-morpholinyl or 1-loweralkyl-4-piperazinyl; Y is alkanoyl of from 1 to 18 carbon atoms, or the radical

70

wherein B is hydrogen, halogen, trifluoromethyl, lower alkyl or lower alkoxy and n is a whole number of from

41

0 to 3; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

12. A compound of the formula

or a non-toxic salt thereof; wherein R' is lower alkyl; Y is alkanoyl of from 1 to 18 carbon atoms, or the radical

wherein B is hydrogen, halogen, trifluoromethyl, lower alkyl or lower alkoxy and n is a whole number of from 0 to 3; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

13. A compound of the formula

or a non-toxic salt thereof; wherein R' and R'' are each lower alkyl or together form with the nitrogen atom attached thereto the radical 1-piperidyl, 1-pyrrolidyl, 4-morpholinyl or 1-loweralkyl-4-piperazinyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

14. A compound of the formula

or a non-toxic salt thereof; wherein R' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

15. A compound of the formula

or a non-toxic salt thereof; wherein R is lower alkyl or the radical

wherein B is hydrogen, halogen, trifluoromethyl, lower alkyl or lower alkoxy and n is a whole number of from

10
5

42

0 to 3; R' and R'' are each lower alkyl or together form with the nitrogen atom attached thereto the radical 1-piperidyl, 1-pyrrolidyl, 4-morpholinyl or 1-loweralkyl-4-piperazinyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

16. A compound of the formula

or a non-toxic salt thereof; wherein R is lower alkyl or the radical

20
25

wherein B is hydrogen, halogen trifluoromethyl, lower alkyl or lower alkoxy and n is a whole number of from 0 to 3; R' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

17. A compound of the formula

30
35
40

or a non-toxic salt thereof; wherein R° is hydrogen or lower alkyl; R' and R'' are each lower alkyl or together form with the nitrogen atom attached thereto the radical 1-piperidyl, 1-pyrrolidyl, 4-morpholinyl or 1-loweralkyl-4-piperazinyl; R''' is lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

18. A compound of the formula

50

or a non-toxic salt thereof; wherein R° is hydrogen or lower alkyl; R' is lower alkyl; R''' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

19. A compound of the formula

70

wherein B is hydrogen, halogen, trifluoromethyl, lower alkyl or lower alkoxy and n is a whole number of from

75

43

or a non-toxic salt thereof; wherein R' and R'' and each lower alkyl or together form with the nitrogen atom attached thereto the radical 1-piperidyl, 1-pyrrolidyl, 4-morpholinyl or 1-loweralkyl-4-piperazinyl; R''' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

20. A compound of the formula

or a non-toxic salt thereof; wherein R' is lower alkyl; R''' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

21. A compound of the formula

or a non-toxic salt thereof; wherein Y is alkanoyl of from 1 to 18 carbon atoms, or the radical

wherein B is hydrogen, halogen, trifluoromethyl, lower alkyl or lower alkoxy and n is a whole number of from 0 to 3; R' and R'' are each lower alkyl or together form with the nitrogen atom attached thereto the radical 1-piperidyl, 1-pyrrolidyl, 4-morpholinyl or 1-loweralkyl-4-piperazinyl; R''' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

22. A compound of the formula

or a non-toxic salt thereof; wherein Y is alkanoyl of from 1 to 18 carbon atoms, or the radical

wherein B is hydrogen, halogen, trifluoromethyl, lower alkyl or lower alkoxy and n is a whole number of from 0 to 3; R' is lower alkyl; R''' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

44

23. A compound of the formula

wherein Y is alkanoyl of from 1 to 18 carbon atoms, or the radical

wherein B is hydrogen, halogen, trifluoromethyl, lower alkyl or lower alkoxy and n is a whole number of from 0 to 3; R' is lower alkyl, benzyl or phenyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

24. A compound of the formula

wherein R' is lower alkyl; RVI is lower alkyl, benzyl or phenyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

25. A compound of the formula

wherein R' is lower alkyl; RVI is lower alkyl, benzyl or phenyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

26. A compound of the formula

wherein R' is lower alkyl; RVI is lower alkyl, benzyl or phenyl; R° is hydrogen or lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

45

27. A compound of the formula

wherein R' is lower alkyl; R^{VI} is lower alkyl, benzyl or phenyl; and X and X' are each hydrogen, lower alkyl, lower alkenyl, halogen, trifluoromethyl, hydroxy, lower alkoxy, mercapto, lower alkylmercapto, loweralkylsulfonyl, sulfamoyl, loweralkylsulfamoyl or diloweralkylsulfamoyl.

28. A compound of the formula

wherein R' is lower alkyl; R''' is lower alkyl; R^{VI} is lower alkyl, benzyl or phenyl; R° is hydrogen or lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

29. A compound of the formula

wherein R is lower alkyl or the radical

wherein B is hydrogen, halogen, trifluoromethyl, lower alkyl or lower alkoxy and n is a whole number of from 0 to 3; R' is lower alkyl; R^{VI} is lower alkyl, benzyl or phenyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

30. A compound of the formula

or a non-toxic salt thereof; wherein R' and R'' are each lower alkyl or together form with the nitrogen atom attached thereto the radical 1-piperidyl, 1-pyrrolidyl, 4-morpholinyl or 1-loweralkyl-4-piperazinyl; R''' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

46

alkoxy, mercapto, loweralkylmercapto, loweralkylsulfonyl, sulfamoyl, loweralkylsulfamoyl or diloweralkylsulfamoyl.

31. A compound of the formula

or a non-toxic salt thereof; wherein R' is lower alkyl; R''' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

32. A compound of the formula

or a non-toxic salt thereof; wherein Z is the radical H OH, OY, NH₂, NH₂SO₂R or

35 R is lower alkyl or the radical

40 wherein B is hydrogen, halogen, trifluoromethyl, lower alkyl or lower alkoxy and n is a whole number of from 0 to 3; R' and R'' are each lower alkyl or together form with the nitrogen atom attached thereto the radical 1-piperidyl, 1-pyrrolidyl, 4-morpholinyl or 1-loweralkyl-4-piperazinyl; R''' is lower alkyl; Y is alkanoyl of from 1 to 18 carbon atoms, or the radical

45 wherein B and n are as defined; A is hydrogen when Z is H, OH, OY, NH₂, NH₂SO₂R or

50 or the radical R''' when Z is OH or OY, or Z and A together form the radicals =NOR°, =NOY or =NNH₂; R' is hydrogen or lower alkyl; and X and X' are each

55 hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

33. A compound of the formula

65

70

75

wherein R' and R'' are each lower alkyl or together form with the nitrogen atom attached thereto the radical 1-piperidyl, 1-pyrrolidyl, 4-morpholinyl or 1-loweralkyl-4-piperazinyl; R^{IV} and R^V are each hydrogen, benzyl, lower alkyl or phenyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

34. A compound of the formula

wherein R' and R'' are each lower alkyl or together form with the nitrogen atom attached thereto the radical 1-piperidyl, 1-pyrrolidyl, 4-morpholinyl or 1-loweralkyl-4-piperazinyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

35. A compound of the formula

wherein R' and R'' are each lower alkyl or together form with the nitrogen atom attached thereto the radical 1-piperidyl, 1-pyrrolidyl, 4-morpholinyl or 1-loweralkyl-4-piperazinyl; X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl; and n is 2 or 3.

36. A compound of the formula

wherein R' is lower alkyl; R^{VI} is lower alkyl, benzyl or phenyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

37. A compound of the formula

wherein R' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

38. A compound of the formula

wherein R' is lower alkyl; X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl; and n is 2 or 3.

39. 10,11 - dihydro - 5 - (3 - dimethylaminopropyl)-5,10-epoxy-5H-dibenzo[a,d]cycloheptene.

40. 10,11 - dihydro - 5 - (3 - dimethylaminopropyl)-5,10 - epoxy - 3 - trifluoromethyl - 5H - dibenzo[a,d]cycloheptene.

41. 10,11 - dihydro - 5 - (3 - diethylaminopropyl) - 3 - dimethylsulfamoyl - 5,10 - epoxy - 5H - dibenzo[a,d]cycloheptene.

42. 10,11-dihydro - 5 - (3-dimethylaminopropyl)-5,10-epoxy-11-hydroxy-5H-dibenzo[a,d]cycloheptene.

43. 10,11-dihydro-5,10-epoxy - 11 - hydroxy-5-(3-methylaminopropyl)-5H-dibenzo[a,d]cycloheptene.

44. 10,11-dihydro - 5 - (3-dimethylaminopropyl)-5,10-epoxy-11-keto-5H-dibenzo[a,d]cycloheptene.

45. 3 α ,12 β -dihydro-2,2-dimethyl - 8 - (3 - dimethylaminopropyl) - 8 - hydroxy - 8H-dibenzo[3,4:6,7]cyclohepta[1,2-d]-1,3-dioxole.

46. 3 α ,12 β -dihydro - 8 - (3 - dimethylaminopropyl)-8-hydroxy-2-phenyl - 8H - dibenzo[3,4:6,7]cyclohepta[1,2-d]-1,3-dioxole.

47. 3 α ,12 β - dihydro - 2 - phenyl-8H-dibenzo[3,4:6,7]-cyclohepta[1,2-d]-1,3-dioxol-8-one.

48. 11-acetoxy-10,11-dihydro - 5 - (3 - dimethylaminopropyl)-5,10-epoxy-5H-dibenzo[a,d]cycloheptene.

49. 11 - acetoxy - 5 - [3 - (carbethoxy-N-methylamino)propyl]-10,11-dihydro-5,10-epoxy - 5H - dibenzo[a,d]cycloheptene.

50. Spiro[10,11-dihydro - 5 - (3-dimethylaminopropyl)-5,10-epoxy - 5H - dibenzo[a,d]cycloheptene]-11,2'-m-dithiane.

51. 10,11-dihydro - 5 - (3-dimethylaminopropyl)-5,10-epoxy-11-hexanoyloxy-5H-dibenzo[a,d]cycloheptene.

52. 10,11-dihydro - 5 - (3-dimethylaminopropyl)-5,10-epoxy-11-hydroxyimino-5H-dibenzo[a,d]cycloheptene.

53. 11-amino-10,11-dihydro - 5 - (3-dimethylaminopropyl)-5,10-epoxy-5H-dibenzo[a,d]cycloheptene.

54. 10,11-dihydro-11-dimethylamino - 5 - (3-dimethylaminopropyl)-5,10-epoxy-5H-dibenzo[a,d]cycloheptene.

55. 11-acetamido-10,11-dihydro-5 - (3-dimethylaminopropyl)-5,10-epoxy-5H-dibenzo[a,d]cycloheptene.

56. 10,11-dihydro - 5 - (3-dimethylaminopropyl)-5,10-epoxy-11-ethylamino-5H-dibenzo[a,d]cycloheptene.

57. 5-[3-(N - carbethoxy - N - methylamino)-propyl]-10,11-dihydro-5,10-epoxy - 11 - hydroxyimino-5H-dibenzo[a,d]cycloheptene.

58. 5-[3-(N - carbethoxy - N - methylamino)-propyl]-10,11-dihydro - 11 - keto-5H-dibenzo[a,d]cycloheptene.

59. 11-amino-5-[3-(N-carbethoxy - N - methylamino)-propyl]-10,11-dihydro-5,10-epoxy - 5H - dibenzo[a,d]cycloheptene.

60. 5-[3-(N - carbethoxy - N - methylamino)-propyl]-10,11-dihydro - 11 - dimethylamino - 5,10 - epoxy-5H-dibenzo[a,d]cycloheptene.

61. 10,11-dihydro - 11 - dimethylamino-5,10-epoxy-5-(3-methylaminopropyl)-5H-dibenzo[a,d]cycloheptene.

62. 10,11-dihydro - 5 - (3-dimethylaminopropyl)-5,10-epoxy-11-hydroxy - 11 - methyl - 5H - dibenzo[a,d]cycloheptene.

63. 10,11-dihydro - 5 - (3-dimethylaminopropyl)-5,10-epoxy-11-hydroxy - 11 - methyl - 5H - dibenzo[a,d]cycloheptene.

49

63. 10,11-dihydro - 5 - (3-dimethylaminopropyl)-5,10-
epoxy-11-methoxyimino-5H-dibenzo[a,d]cycloheptene.

64. 11-acetoxyimino - 10,11 - dihydro - 5 - (3-dimethyl-
aminopropyl)-5,10-epoxy-5H-dibenzo[a,d]cycloheptene.

65. 10,11-dihydro - 5 - (3-dimethylaminopropyl)-5,10-
epoxy-11-methanesulfonamido - 5H - dibenzo[a,d]cyclo-
heptene.

66. 11 - amino-10,11-dihydro-5,10-epoxy-5-(3-methyl-
aminopropyl)-5H-dibenzo[a,d]cycloheptene.

67. 10,11 - dihydro-5,10-epoxy - 11 - hydroxyimino-5-
(3-methylaminopropyl)-5H-dibenzo[a,d]cycloheptene.

68. 10,11 - dihydro-5,10-epoxy - 11 - keto-5-(3-methyl-
aminopropyl)-5H-dibenzo[a,d]cycloheptene.

69. 11-acetoxy-10,11-dihydro - 5 - (3-methylaminopropyl)-
5,10-epoxy-5H-dibenzo[a,d]cycloheptene.

70. 11-benzoyloxy-10,11-dihydro - 5 - (3-dimethylami-
nopropyl)-5,10-epoxy-5H-dibenzo[a,d]cycloheptene.

71. 10,11-dihydro - 5 - (3-dimethylaminopropyl)-5,10-
epoxy-11-hydroxy-5H-dibenzo[a,d]cycloheptene N-oxide.

72. 10,11-dihydro - 5 - [3-(N-carbethoxy - N - methyl-
amino)-propyl]-5,10-epoxy - 11 - hydroxy - 5H - dibenzo-
[a,d]cycloheptene.

73. 10,11-dihydro - 5 - (3-dimethylaminopropyl)-5,10-
epoxy-11-hydrazono-5H-dibenzo[a,d]cycloheptene.

74. 11-acetoxy-10,11-dihydro - 5 - (3 - dimethylamino-
propyl)-5,10-epoxy-11-methyl - 5H - dibenzo[a,d]cyclo-
heptene.

75. 5-[3-(N - carbethoxy - N - methylamino)-propyl]-
10,11-dihydro-5,10-epoxy - 11 - hydroxy - 11 - methyl-5H-
dibenzo[a,d]cycloheptene.

76. 10,11-dihydro-5,10-epoxy - 11 - hydroxy-11-methyl-
5-(3-methylaminopropyl)-5H-dibenzo[a,d]cycloheptene.

77. A compound of the formula

wherein R' is lower alkyl; R''' is lower alkyl; and X and X' are each hydrogen, lower alkyl, lower alkenyl, halogen, 45 trifluoromethyl, hydroxy, lower alkoxy, mercapto, loweralkylmercapto, loweralkylsulfonyl, sulfamoyl, loweralkyl-

78. A compound of the formula

wherein R' is lower alkyl; R''' is lower alkyl; RVI is lower alkyl, benzyl or phenyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or di-
loweralkylsulfamoyl.

79. A compound of the formula

50

or a non-toxic salt thereof; wherein R' and R'' are each lower alkyl or together form with the nitrogen atom attached thereto the radical 1-piperidyl, 1-pyrrolidyl, 4-morpholinyl or 1 - loweralkyl - 4 - piperazinyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

80. A compound of the formula

or a non-toxic salt thereof; wherein R' is lower alkyl; and X and X' are each hydrogen, lower alkyl, lower alkenyl, halogen, trifluoromethyl, hydroxy, lower alkoxy, mercapto, loweralkylmercapto, loweralkylsulfonyl, sulfamoyl, loweralkylsulfamoyl or diloweralkylsulfamoyl.

81. 10,11-dihydro-5,10-epoxy-5-(3-methylamino-
propyl)-5H-dibenzo[a,d]cycloheptene.

82. Trans 10,11-dihydro-5-(3-dimethylaminopropyl)-
5,10-epoxy-11-hydroxy-5H-dibenzo[a,d]cyclo-
heptene.

83. Trans 10,11-dihydro-5,10-epoxy-11-hydroxy-
5-(3-methylaminopropyl)-5H-dibenzo[a,d]cyclo-
heptene.

84. Trans 11-acetoxy-10,11-dihydro-5-(3-dimethyl-
aminopropyl)-5,10-epoxy-5H-dibenzo[a,d]cyclo-
heptene.

85. Trans 10,11-dihydro-5-(3-dimethylaminopropyl)-
5,10-epoxy-11-hexanoyloxy-5H-dibenzo[a,d]
cycloheptene.

86. Trans 11-amino-10,11-dihydro-5-(3-dimethyl-
aminopropyl)-5,10-epoxy-5H-dibenzo[a,d]cyclo-
heptene.

87. Trans 11-acetoxy-10,11-dihydro-5-(3-methyl-
aminopropyl)-5,10-epoxy-5H-dibenzo[a,d]cyclo-
heptene.

88. Syn 10,11-dihydro-5-(3-dimethylaminopropyl)-
5,10-epoxy-11-hydroxyamino-5H-dibenzo[a,d]
cycloheptene.

UNITED STATES PATENT OFFICE
CERTIFICATE OF CORRECTION

Patent No. 3,494,935

Dated February 10, 1970

Inventor(s) Marcia E. Christy

It is certified that error appears in the above-identified patent and that said Letters Patent are hereby corrected as shown below:

Insert in patent heading after zip code of inventor "18944" -- , assignor to Merck & Co., Inc., Rahway, N.J., a corporation of New Jersey --. Column 7, line 30, the word "stability" should read "availability"; line 56, "5,11" should read "5,10". Column 14, product (3) of listing, "cimethyl" should read "dimethyl". Column 18, line 16, the repeated word of "cycloheptene" should be deleted; line 62, after "dibenzo[a,d]" insert -- cycloheptene --. Column 23, line 62, "0°.358" should read "0.358". Column 27, line 46, "N, 6.89" should read "N, 8.69". Column 29, line 16, insert -- Example 45 --; line 17, insert -- 10,11-Dihydro-5-(3-dimethylaminopropyl)-5,10-epoxy-11-ethylamino-5H-dibenzo[a,d]cycloheptene --; line 42 of Example 46, under product listing, "5-(d-" should read "5-(3-". Column 30, line 25, "80 mg." should read "180 mg.". Column 39, line 60, insert after the word "is" -- alkanoyl --. Column 40, claim 9, "NOH°" should read "NOR°". Column 42, line 23, insert after the word "halogen" -- , --. Column 45, lines 55-56, "loweralkylsulfamoyl" should read "loweralkylsulfonyl". Column 49, line 47, after the word "loweralkyl-" insert -- sulfamoyl or diloweralkylsulfamoyl --. Column 50, line 44, the word "hydroxyamino" should read "hydroxyimino".
